A technical line drawing of a mechanical assembly. It features a central vertical rod with a horizontal slot. Two horizontal bars, labeled 171 and 172, are positioned above and below this slot. On the left side, there are two cylindrical components, each with a flange and a central hole, labeled 165. On the right side, there is a similar cylindrical component labeled 167. A large, coiled spring is located on the right side, with its ends attached to the central rod and the cylindrical component 167. A small circular component is attached to the right end of the central rod. The drawing is annotated with various numbers: 165, 171, 172, 167, 164, 163, 162, and 161.

UNITED STATES PATENT OFFICE.

CHARLES L. KRUM AND HOWARD L. KRUM, OF CHICAGO, ILLINOIS.

SELECTIVE TELEGRAPH SYSTEM AND APPARATUS.

1,232,045.

Specification of Letters Patent.

Patented July 3, 1917.

Application filed November 29, 1909. Serial No. 530,455.

To all whom it may concern:

Be it known that we, CHARLES L. KRUM and HOWARD L. KRUM, citizens of the United States, and residents of the city of Chicago, county of Cook, and State of Illinois, have invented certain new and useful Improvements in Selective Telegraph Systems and Apparatus, of which the following is a specification.

10 The invention relates to selective telegraph systems and apparatus and more particularly to printing telegraphs and seeks to provide improved means by which the signals or characters of a message can be transmitted rapidly from one station and received or recorded with certainty at a distant station. Further objects of the invention are to provide an improved transmitter and a receiver comprising improved selecting and 15 printing apparatus. The invention consists in the features hereinafter set forth, illustrated in the preferred form and arrangement in the accompanying drawings and more particularly pointed out in the appended claims.

In the preferred form, the transmitter and receiver are combined in a single machine, one such machine being located at each station.

20 In the drawings, Figure 1 is a longitudinal section of the improved apparatus with the base portion of the machine shown in section on the line 1—1 of Fig. 5 and the upper portion of the machine shown in section on the line 1—1 of Fig. 9. Fig. 2 is a detail view of the printing mechanism with parts shown in section on the line 2—2 of Fig. 9. Fig. 3 is a detail view of the type-wheel centering device with parts shown in section on the line 3—3 of Fig. 1. Fig. 4 is a detail view of the type-wheel inking device. Fig. 5 is an inverted plan view of the base portion of the apparatus illustrating the transmitter. Fig. 6 is a detail view of a 25 portion of the transmitter, parts being shown in elevation and parts in section on the line 6—6 of Fig. 1. Fig. 7 is a detail view with parts shown in section on the line 7—7 of Fig. 6. Fig. 8 is a detail plan section on the line 8—8 of Fig. 7. Fig. 9 is a front elevation of the upper portion or receiver of the apparatus with the top plate in section. Fig. 10 is a plan section of the upper or receiving portion of the apparatus with parts 30 in section on the line 10—10 of Fig. 9. Fig. 11 is a detail view with parts in section on

the line 11—11 of Fig. 10. Fig. 12 is an elevation of the right-hand end of the upper or receiving portion of the apparatus. Fig. 13 is a vertical section on the line 13—13 of Fig. 12. Fig. 14 is a horizontal section on the line 14—14 of Fig. 12. Fig. 15 is a detail view of the upper centering device for the type mechanism. Fig. 16 is a vertical section on the line 16—16 of Fig. 10. Fig. 17 is a detail section on the line 17—17 of Fig. 10. Figs. 18, 19 and 20 are detail views of three of the selector plates. Fig. 21 is a diagram of the transmitting, selecting and receiving circuits.

35 The transmitter is arranged within the base frame A of the machine which is mounted upon the feet a. The receiving mechanism is arranged within the upper portion of the frame which comprises a bottom plate B, a top plate B' and a series of corner posts b extending between and fastened to the bottom and top plates. This upper frame is detachably secured to the base frame A by screws extending through the upper corners of the base frame into the lower ends of the posts b.

40 A series of horizontal key-levers C are arranged within the upper portion of the base frame A. At their rear ends, the transmitting key-levers C extend between the down-turned teeth of a transverse comb bar 1 secured to the upper rear portion of the base frame. A fulcrum pin or rod 2 extends through the rear ends of the key-levers and through forwardly-projecting lugs 3 on the comb bar 1 and is held in position by set screws 4 extending through the lugs into engagement therewith. At their forward ends, the key-levers extend through a transverse opening in the front wall of the base frame and over a forward extension a'. A transverse guiding comb bar 5 is arranged at the front portion of the base frame and the forward ends of the key levers are upturned and carry a series of keys C' which are arranged in rows or banks similar to the arrangement of the keys of an ordinary type-writing machine. A transverse bar 6 extends between the sides of the base frame below the key-levers and a series of U-shaped springs 7 extend between this bar and the key-levers C and normally uphold the latter with their forward ends against a transverse member or stop-bar 8 at the upper front portion of the base frame.

45 In the present system, the characters or

signals are represented by permutations of a definite number of impulses of opposite polarity and, in accordance with the preferred plan, each character or complete signal is represented by a particular permutation of five impulses of opposite polarity and the transmitting keys are arranged to control a set of five signal selecting switches or pole changers. These switches or pole changers are preferably in the form of spring-arms D, (see Figs. 1 and 6) that are mounted at their lower ends upon a transverse bar 9 arranged above the key-levers and fixed at its ends to a pair of uprights 10. These five pole changers are variably operated by the finger-keys to control the selection of the different permutations. The transmission of the selected permutations is effected by suitable means as hereinafter set forth. The operation of said transmitter means is controlled or initiated by a sixth spring switch-arm d which is also mounted on the bar 9 with the set of five selecting switches D. The uprights 10 rise from a cross-bar 11 which extends above the key-levers C and is supported upon the upper ends of two uprights 12 that extend upwardly, each between a pair of key-levers, from two side-plates or bars 13 (see Figs. 1 and 2) that extend between and are secured to the cross-bar 6 and the front portion of the base frame A. The set of switches D and the switch d are insulated from their supporting bar 9 and extend upwardly therefrom between a pair of cross-bars 14 that are fixed at their ends to the upper ends of the uprights 10. These bars carry the insulated, adjustable, front and back contact screws for the switch-arms. The contact screws for the set of pole-changing switches D on one of the bars 14 are connected to one side of a divided battery and the front contacts therefor on the other bar 14 are connected to the opposite side of the battery. The switch-arms D and d normally engage their back contacts, as shown in Fig. 1, and are shifted out of engagement therewith and into engagement with their front contacts by a series of cam disks d' which are rotatably mounted upon a transverse support 15 extending between the uprights 10 and are provided with cam lugs 16 which are arranged to engage offsets 17 formed in the switches D and d. The cam disks d' are insulated from the cross-support 15 and from a series of disks or plates 19 secured to the faces thereof. The cam disks d' with the plates 19 secured thereto, are held in proper position on the cross support 15 by a series of spacing sleeves 18. A series of U-bars or bails D' are arranged below the key-levers C (see Figs. 1 and 5), and are pivoted at their rear ends upon lugs 20 fixed to the cross-bar 6. There are six bails in the form shown and they are respectively connected to the insulated disks 19 of the switch-operating cams d' by a set of links 21 which are riveted to the front cross-bars of the bails at their lower ends and are provided with pins 22 and spring-clips 23 at their upper ends which engage the lower ends of a set of links 24 that are pivotally connected at their upper ends to the disks 19 of the switch-operating cams d'. A set of U-shaped springs 25 extend between the cross-bar 6 and the side-arms of the bails D' and serve to hold the bails and the switch-operating cams d' in normal position with the bails 20 against a series of adjustable stop-screws 26. These adjustable stop-screws are carried on two arms 27 that are fixed at their forward ends to a transverse bar 28 and project rearwardly therefrom. The bar 28 extends between the side portions of the base frame A near the forward end thereof. The outside bail D' is connected to the operating cam for the transmitter initiating switch d and the other bails are connected to the actuating cams of the pole-changing or permutation selecting switches D. Each key is arranged to operate the outside bail and thereby shift the switch d, and each is arranged to operate a particular combination of the other bails to so operate the set of switches D as to select a combination or a permutation of impulses or code signals which represents the character of that particular key. The selective operation of the bails by means of the keys is effected by a series of character type C² fixed to the keys and each having a series of downwardly extending teeth 29. Each of these character type is arranged to operate the outside bail to thereby shift the switch d and the teeth 29 of the several type are arranged to operate different combinations of the remaining bails to selectively operate different combinations of the pole-changing switches D; so that permutations of five impulses of opposite polarity may be selected by the switches D and the selected permutations transmitted to the line. While the movement of the keys is initiated by the operator, the shift thereof is preferably completed by a combined actuator and lock-out in the form of a transverse universal bar E. This universal bar is angular in cross-section and is fixed at its ends to a pair of upright pins 30. These pins are pivoted at their lower ends upon the forward ends of two crank-arms 31 that are mounted upon the ends of a transverse shaft 32 journaled in the side-plates 13. The upper ends of the pins 30 extend through openings in two fixed guide-lugs 33, so that the pins and the universal bar E move in vertical direction. An arm 34 on the cross-shaft 32, is connected to one end of

a spring 35. The opposite end of the spring is connected to an adjusting screw 36 mounted on a lug 37 on one of the side-plates 13. This spring holds the shaft 32 and universal bar E in normal position with lugs 38 on the ends of the universal bar engaging adjustable stop screws 39 that are carried by the fixed lugs 33. The upper end of the arm 34 is engaged by a horizontal actuating rod e which is arranged to slide through a suitable guide opening in the cross-bar 6 and, at its rear end, is adjustably threaded through a cross-bar 40 that is connected to the cores e' of a double spool, solenoid magnet E'. The spools of this magnet are secured to the cross-bar 6 and project rearwardly therefrom. The actuating rod e is adjustably threaded through the cross-bar 40, as stated, and is held in adjusted position relatively thereto by a lock-nut 41. A spring 42 coiled about the rod extends between the cross-bar 6 and a collar 43 on the rod and holds the end of the rod against the upper end of the arm 34 on the shaft 32. The circuit of this magnet is controlled by the switch d which, as stated, is operated whenever any key is shifted, so that the magnet E' will be energized to shift the rod e and thereby, through the medium of the connections described, pull down the universal actuator bar E. The key levers are coupled to the universal bar E by a series of latches e² which are pivoted thereto and depend therefrom in front of the transverse bar 28. A set of springs 44 extend between the key-levers of the latches to normally press the latter toward the cross-bar 28 and away from the actuator bar E. The lower ends of the latches extend through a comb bar 45 attached to the lower edge of the cross-bar 28, and at their extreme lower ends, the latches are provided with forwardly projecting lugs 46. The back edges of the latches are provided with cam lugs 47 which coöperate with the beveled upper edge of the transverse bar 28, when the keys are depressed, to force the latches forwardly against the tension of the springs 44 and thereby move the lugs 46 thereon below the lower edge of the actuator bar E. The preliminary shift of any key is sufficient to bring the latch thereon in this manner into engagement with the actuator bar and is also sufficient to shift the switch d and thereby energize the magnet E'. The magnet then shifts the universal actuating and lock-out bar E to complete the shift of the selected key and character type C² mounted thereon and, as the bar E moves down in front of the ends of the latches e² of the remaining keys, the latter are locked against operation until the magnet E' is deenergized and releases the actuator bar E and the selected key to permit the latter to be restored to normal position. The circuit of

the magnet E' is held closed until the transmission of the selected signal is completed, so that by this arrangement it is impossible to cause the signals to overlap on the line circuit by any excessively rapid operation of the keys. Moreover, since the operator merely initiates the operation of the keys, the touch is light and such as to permit the rapid operation of the keys in transmitting a message. 75

To provide a uniform tension on the key-levers and bails operated thereby, a cross-shaft 48 is journaled in the side-bars or plates 13 and is provided with forwardly projecting arms 49 (see Figs. 1 and 5) having outwardly projecting pins 50 on their ends which extend beneath the side-arms of the several bails. A depending arm 51 on this shaft is connected by a spring 52 to a stud on one of the side-plates 13. The tension of this spring is applied to all the bails and keys as they are depressed and tend to render the touch uniform, and also tend to increase the resistance to the depression of the keys at the lower ends of their shift. 80 90

A spring-arm 53 is secured at its inner end to the arm 51 and at its outer end engages an adjusting screw 54 on the end of the arm 51. At the end of the down stroke of any key, this spring is arranged to engage an adjusting screw 56 on a lug 57 that is fixed to one of the side-bars or plates 13. By adjusting the screws 54 and 56 the resistance to the depression of the keys at the lower ends of their movement can be adjusted. 95 100

This spring serves to throw back the keys quickly and give a desired repulser action thereto that assists the operator in rapidly manipulating the keys. 105

Besides the regular keys, the key-board of the transmitter is provided with two special keys 58 and 59 (see Fig. 5) for transmitting special signals to effect the carriage return and line space mechanisms of the printing mechanism. A space key or bar 60 is mounted on two arms 61 that are pivoted at their inner ends to depending clips 62 on the cross-bar 8. The space-bar or key is arranged to engage a stop-pin 63 upon the forward extension "a" of the base frame and one of the arms 61 thereof is provided with a pin 64 that is arranged to engage the forward end of a special key-lever C² but having a proper type thereon to send a special combination to effect the letter-space, feed of the printing mechanism to thereby form the spaces between the words of the message. 110 115 120

The key-board is also provided with two other special keys F F' for effecting the 125 "upper case" or capitals and figure shifts of the printing mechanism. The key-levers f f' of these keys are arranged at one side of the series of key-levers C, but are not provided with character type C² to operate the 130

bails D'. These key-levers are arranged to operate two special switch-arms f^2 and f^3 (see Figs. 6, 7 and 8) which are mounted upon but insulated from a pair of lugs 65 on the lower ends of two uprights 66. These uprights are mounted on the left-hand end of the transverse bar 11 and are connected at their upper ends by two transverse bars 67 which carry the adjustable, insulated, front and back contact screws 68 for the switch-arms f^2 and f^3 . The switch-arm f^2 is a pole-changing switch similar to the switch-arms D, whereas the switch-arm f^3 is arranged to initiate the operation of the transmitting means and, in that respect, is similar to the switch-arm d. The switch-arms f^2 and f^3 are operated by two cam disks F² and F³ which are rotatably mounted upon a cross support 69 extending between the uprights 66. These cam disks, like the cam disks d', are provided with lugs 16 arranged to engage offset or bent portions 17 in the switch-arms f^2 and f^3 . Each of these cam disks is insulated from the cross support 69 and each is provided with inner and outer face plates or disks 70 and 71 secured to the opposite faces thereof but insulated therefrom as shown. Springs 72 coiled about the cross support 69 or about sleeves thereon, are fixed at their outer ends to the side uprights 66 and at their inner ends to the disks or plates 71, so that these actuating cams are held in normal position with stop-pins 73 on the inner face-plates 70 engaging a stop-plate 74 that is secured to the rear face of a cross-bar 75 extending between the uprights 66. The special shifting key-levers f f' are provided with shifter arms for the cams F² and F³. Two of these shifter arms 76 and 77 are pivoted to the key-levers f and f' and extend upwardly in front of the cams F² and F³ and are provided with hooks 78 and 79 which are arranged to engage pins 80 and 81 upon the inner face plates 70 of the cams. Two shifter arms 82 and 83 are pivoted to the key-levers f and f' and extend upwardly behind the cams F² and F³ and are provided with beveled upper end portions 84 and 85 which are arranged to operate the cam disks F² and F³ through the medium of inwardly projecting pins 86 and 87 on the inner face plates 70 of the cam disks. The shifter arms 76, 77, 82 and 83 extend upwardly through slots in a pair of guide lugs 88 fixed to the cross-bar 75 and springs 89 extend between the arms so that they are spring-pressed toward one another and yieldingly held into engagement with the oppositely arranged lugs 88 which form stops to limit the inward movement of the shifter arms toward the disk cams F² and F³ operated thereby.

The hooks 77 and 79 are beveled upon their upper faces and are provided with

lower abrupt faces so that they engage the pins 80 and 81 upon the down stroke of the key-levers F and F' to oscillate the cams F² and F³ and thereby operate the switch-arms f^2 and f^3 . The throw of the key-levers is such that the hooks 78 and 79 engage the pins 80 and 81, to operate the cams and move on past the pins, so that the springs 72 restore the cams to normal position. On the up stroke of the key-levers, the beveled faces of the hooks engage the pins 80 and 81 and they pass idly over the pins. The hook 78 is double and engages both pins 80 and 81 on the down stroke of the key-lever f and thereby operates both cams F² and F³ and both switch-arms f^2 and f^3 . The hook 79 is arranged to engage only the pin 81 of the cam F³ and hence only operates the switch arm f^3 . The upper end portions 84 and 85 of the shifter arms 82 and 83 are provided with abrupt upper faces and beveled lower faces, so that these shifter arms pass idly over the pins 86 and 87 on the down stroke of the key-levers f and f' but engage the pins and rock the cams F² and F³ to shift the switches f^2 and f^3 on the up stroke of the keys. At the ends of the up stroke of the keys, the beveled end portions of the shifter arms 82 and 83 are disengaged from the pins 86 and 87 to release the disk cams and permit the springs 72 to restore them to normal position with the stop-pins 73 thereon in engagement with the plate 74. The upper end portion 85 of the shifter arm 83 is double and is arranged to engage both pins 86 and 87 on the up stroke of the key-lever f' and thereby shift both switch arms f^2 and f^3 , whereas the upper end portion 84 of the shifter arm 82 is single and operates only on the pin 87 of the cam F³, so that the switch f^3 is alone operated. By reason of this arrangement, the key-lever f will shift both switches f^2 and f^3 on its down stroke and the switch f^3 alone on its up stroke, while the key-lever f' will shift the f^3 alone on its down stroke and both the switches f^2 and f^3 on its up stroke. At the end of the up and down strokes of either key, springs 72 restore the cams to normal position. These switches, as hereinafter set forth, are arranged to transmit special signals to shift the type mechanism to thereby press capitals and figures and to restore the printing mechanism so that "lower case" letters will be printed. These special key-levers f and f' do not, as stated, operate the bails D'; neither are they operated by the common actuator bar E, so that when one of the special keys is shifted it does not prevent the operation of the other keys of the machine. When the operator desires to transmit capitals or figures, he depresses one or the other of these shift keys and holds it depressed while he operates the proper character keys in a manner similar to the operation of the

shift mechanism of an ordinary typewriter, the depression of the shift key, as stated, sending the proper combination to effect the shift of the type mechanism at the receiver, 5 and the release of the key pending the proper combination of impulses to restore the type mechanism.

While the operation of one of the character keys does not lock out the shift keys, it 10 is desirable to provide means to prevent the simultaneous operation of both shift keys. For this purpose, the comb bar 5, through which the key-levers extend, carries an interlocking disk 90 on its face (see Fig. 6) which 15 is connected thereto by a screw 91 extending through a transverse slot in the disk. The comb bar is also preferably provided with two pins 92 which engage the upper and lower edges of the disk. The disk is so arranged, with reference to the key-levers f and f' that, when one is depressed, the disk is shifted laterally to a slight extent and locks the other key-lever against operation until the depressed shift key has been restored to normal position. The special shift 25 keys f and f' are upheld in normal position by two cushion springs 93 (see Figs. 1 and 5) extending between these key-levers and a lug 94 on one end of the transverse bar 6. 30 The frames on the transverse bar 11 which support the switches D , d , f^2 and f^3 and their operating cams extend upwardly through an opening in the front part of the bottom plate B of the upper portion of the frame, as 35 shown in Fig. 1. The rotary operating cams, with the lugs 16 thereon, are so arranged that the initial movement of any of the keys will quickly move the switches to their shifted position and hold them firmly 40 in engagement with their front contacts during the continued movement of the keys and until the keys are restored to normal position and until the permutation or combination of impulses selected by the operation of 45 any key has been transmitted to the line circuit.

The top plate B' of the machine is provided with a pair of upwardly projecting side-plates or brackets 95 between the upper, 50 forward portions of which is arranged a horizontal, cylindrical platen G that is mounted on a shaft g , the ends of the shaft being journaled in the side-plates or brackets 95. The upper, rear portions of the side- 55 plates 95 are provided with notches 96 adapted to receive the pintles of a paper roll, as indicated in dotted lines in Fig. 1. The paper is passed to the platen over an inclined guide-plate 97 that engages supports 113 on the side-plates 95. The paper 60 is held in contact with and is guided about the platen by two longitudinally extending feed rollers 98 and 99 which engage the under side of the platen at the front and rear thereof respectively and by two paper

guide-fingers 100. The shafts of the rollers 98 and 99 are journaled at their ends in two curved arms 101 which also carry a curved guide-plate 102 intermediate the rollers. The arms 101 are mounted on the forward 70 ends of a pair of spring-arms 103 which are secured at their rear ends to lugs 104 on the side brackets 95. These arms yieldingly press the feed rollers 98 and 99 against the platen. The forward ends of the spring 75 arms 103 extend through notches or recesses 105' in a rotary releasing rod 105 (see Figs. 1 and 9) that is journaled at its ends in the side brackets 95 and is provided at one end with an arm or finger piece 106. By rotating the rod 105 by means of the finger piece, the forward ends of the spring-arms 103 are depressed and the feed rollers 98 and 99 are moved away from the platen. The paper fingers 100 are provided with 80 rectangular sleeves 107 that slidably engage a supporting rod 108 extending between the side brackets 95 above the platen. The paper fingers extend downwardly and forwardly from the rod 108 about the platen 90 and their forward, lower ends engage a paper scale 110 that is pivoted at its ends in the front ends of the arms 101. At their upper ends, the paper fingers are provided with inwardly projecting portions 109 and 95 the sleeves 107 thereon are provided with finger-pieces 111, so that they may be readily shifted along the supporting rod 108. The paper fingers guide the paper as it passes from the front feed rollers 98 up over the 100 front face of the platen and the paper then passes beneath the rod 108 and over a fixed guide-plate 112 that extends between the side-plates 95.

The long paper guide-plate 97 directs the 105 paper into engagement with the platen, is employed for separate sheets. It is preferably removably mounted in slotted supports 113 on the inner faces of the side brackets 95 and when a paper roll is employed, this 110 guide-plate is removed and the paper passes from the roll over a narrow guide-plate 114 that extends between and is fixed to the side brackets 95.

The shaft g of the platen is provided at 115 its ends with the usual finger-pieces g'' and on one end it is provided with a line-space ratchet g' . A detent arm 115 pivoted on the adjacent side bracket 95 is provided with a roller 116, and a U-shaped spring 117 engaging the arm normally holds the roller into engagement with the ratchet g' . A stop pawl g^2 is mounted at its lower end on a short shaft 118 that is journaled in the adjacent side bracket 95 and a feed pawl g^3 120 is pivoted to the upper end of the stop pawl. A spring coiled about the shaft 118 normally holds the stop pawl in normal position out of contact with the ratchet wheel g' and against a stop pin 119 on the side bracket 125 130

95, and a spring coiled about the pivot of the feed pawl g^3 holds it in normal position out of contact with the ratchet wheel with an upwardly projecting arm g^4 thereon in 5 engagement with the stop pin 119. An arm 120 on the shaft 118 (see Figs. 1 and 2), is arranged to be engaged by the upper end of a vertical rod 121 which slides through an opening on the top plate and is adjustably 10 threaded at its lower end into a cross-bar 122 that connects the cores G' of a double spool, solenoid magnet G^2 . The spools of this magnet are fixed at their upper ends to the top plate B' of the machine. A spring 15 123 coiled about the upper end of the rod 121 extends between the top plate and a collar on the rod and upholds the latter into engagement with the arm 120.

When a special combination of impulses 20 is transmitted, the magnet G^2 is energized to draw up the bar 122 and thereby rock the shaft 118 and the pawls carried thereby toward the ratchet wheel g' . As the arm or stop pawl g^2 is swung away from the stop pin 119, the spring of the feed pawl g^3 throws it into engagement with the ratchet wheel and the further forward movement of the stop pawl g^2 advances the line space ratchet g' one notch or until it is engaged 25 by the upper, pointed end of the stop pawl g^2 . The platen and the paper thereon are thereby advanced one step in line space direction.

The type are preferably arranged, as 30 shown, upon a type wheel or carrier H with the "lower case" letters in one row, the capitals in another and the figures and punctuation marks in a third row. In the particular form shown, the "lower case" letters 35 are in the top row, the capitals in the middle row and the figures and punctuation marks in the lower row. The type wheel is fixed to the upper end of a spindle h which is mounted to slide longitudinally through 40 a hollow shaft 124 that is journaled at its upper end in the upper end of a swinging arm j . The lower, yoke-shaped end of this arm is pivoted between a pair of upwardly projecting lugs 125 on a sliding carriage J 45 and the lower end of the shaft 124 is connected by a universal coupling 126 to a short, vertical shaft 127 (see Fig. 9) that is journaled in the carriage. The carriage is mounted to slide upon two horizontal 50 supporting rods or shafts 128 and 129 that extend between and are journaled in the upper portions of a pair of side-plates or brackets 130 (see Fig. 9) that rise from the bottom plate B . The carriage is also provided with a depending lug 131 that engages a third transverse shaft l which also extends between and is journaled in the side-plate 130. The shafts 128, 129 and l are 55 preferably square in cross-section and collars 132, journaled in the lug 131 and in

side lugs 133 of the carriage J , engage the shafts to rotate therewith but are flanged to engage the lugs 132 and 133, so that they slide along the shafts with the carriage. A beveled pinion 134 connected to the collar 132 on the shaft l , engages a beveled pinion 135 on the lower end of the short vertical shaft 127, so that the rotation of the shaft l will rotate the shafts 127 and 124 and the type-wheel H to bring the proper 75 type thereon opposite the printing point on the platen. The type wheel H and spindle h rotate with the shaft 124 but are free to slide vertically thereon to bring any one of the rows of type on the wheel opposite 80 the printing point. A collar 136 is mounted to slide on the shaft 124 and is connected by a pin 137 with the spindle h within the shaft 124, the pin 137 extending through a longitudinal slot 138 in the shaft (see Fig. 85 9). The spindle h is thus keyed to rotate with the shaft 124. To further insure the rotation of the type-wheel with the shaft 124 but at the same time permit its vertical shift independently thereof, the shaft is provided at its upper end with an arm 139 which extends upwardly through an eccentric opening in the type wheel. The type wheel is shifted vertically by a fork 140 which engages a groove in the collar 136 and 90 is fixed to a shifting spindle 141 that is arranged to slide through two lugs 142 formed upon the upper and lower portions of the swinging arm j . The lower end of the spindle 141 is connected by a link 143 to the end of a bent arm 144 that extends inwardly from one of the collars 132 on the shaft 129, so that by rotating this shaft the type wheel can be shifted in vertical direction. It will be understood that the parts 100 of the type wheel shift mechanism thus far described move with the sliding carriage J in letter space direction.

At its left-hand end, the shaft 129 (see Figs. 1, 2 and 9) is provided with a forwardly projecting arm 145 connected by a link 146 to the end of an arm 147 on a rock shaft h' . This shaft is journaled in two uprights 148 that are mounted upon the horizontal portion of an upwardly projecting 110 plate or bracket 149 that is fixed to the bottom plate B . A spring 150 coiled about the right-hand end of the shaft 129 (see Figs. 9 and 10) is fixed at its ends to the shaft and to the adjacent side-plate 130 120 and normally holds the type wheel shift mechanism in position with the top row of "lower case" type on the wheel H opposite the printing point and with the arm 147 against a stop-screw 151 (see Figs. 2 and 125 9). This stop-screw is adjustably threaded through the laterally extended end portion of an upright 152 that rises from the bottom plate B .

The rock shaft h' is provided with a pair 130

of upwardly projecting arms h^2 which are arranged to be engaged by two longitudinally shiftable actuator rods h^3 . These rods extend through a pair of single spool magnets H' and H^2 . The frames 153 of these magnets are secured to the upright plate 149 and the magnet projects rearwardly therefrom. Each of these magnets is provided with an inner, fixed core section 154 through which the actuating rods h^3 loosely extend, and with an outer, movable core section 155 through which the rods are adjustably threaded. Lock-nuts 156 hold the movable core section 155 and the actuating rods h^3 in adjusted relation. Springs 157 on the inner ends of the rods extend between the upright plate 149 and collars on the rods and hold them and the movable core sections 155 in normal position with the inner ends of the rods engaging the arms h^2 on the rock-shaft h' . The shift of the actuator rods and of the movable core section 155 is limited by the engagement of the latter with the fixed core section 154 and by adjusting the movable core sections, the throw of the actuating rods h^3 and the throw imparted thereby to the rock-shaft h' can be adjusted, and is so arranged that one of the magnets will operate the shift mechanism to elevate the type wheel one step and bring the second row of capital letters opposite the printing point, while the other magnet will elevate the type wheel to a sufficient extent to bring the third row of figure and punctuation type opposite the printing point. With the particular arrangement shown, the magnet H^2 is the "capital shift" magnet and the magnet H' is the "figure shift" magnet.

By the operation of the shift-keys F and F' of the transmitter, the proper signals or combinations of impulses are transmitted to select one or the other of these shift magnets H' and H^2 and the circuits of these magnets remain closed as long as either of the shift keys of the transmitter is held depressed and is not opened until the depressed shift-key is released to thereby transmit a proper releasing signal.

The shafts 128 and 129 and the sliding carriage J mounted thereon are arranged below the top-plate B' of the machine while the pivoted arm j with the type wheel H and shaft 124 mounted thereon extends upwardly through a transverse slot or opening 159 (see Figs. 1 and 9) formed in the top plate. The side-plates 130 within which the shaft 128, 129 and j are journaled, are securely fastened at their lower ends to the base plate B and are connected at their upper ends by a transverse brace-rod 160.

The type wheel and the type wheel adjusting shaft l which rotates it, are preferably held in central position and means are provided for rotating the shaft and type wheel in opposite directions from normal

to bring the proper type to the printing point. At its right-hand end, the type wheel adjusting shaft l is provided with a pinion l' (see Figs. 9, 10 and 12) which is arranged to be engaged by a gear segment 70 l^2 . This gear segment is fixed at its lower end to a rock-shaft l^3 that is journaled at its outer, right-hand end in one of the plates 130 and at its inner, left-hand end in a forwardly projecting lug 161 of an upright bracket 162 that is fixed to the bottom plate B. A transverse arm l^4 is fixed to the left-hand end of the shaft l^3 and the opposite ends of this arm are arranged to be engaged by two actuator rods l^5 that are arranged 75 to slide through suitable guide openings in the bracket 162 and are adjustably threaded at their rear ends to cross-bars 163. These cross-bars are connected respectively to the movable cores L^2 , L^2 of two double spool solenoid magnets L and L' mounted on the bracket 162 and projecting rearwardly therefrom. Springs 164 are coiled around the actuator rods l^5 and extend between the face of the bracket 162 and collars on the 80 rods to hold the latter and the movable cores of the magnet L and L' in position with the forward ends of the rods engaging the cross-arm l^4 . The arrangement of these type-adjusting magnets is most clearly 85 shown in Fig. 11. By energizing one or the other of these magnets, the type-adjusting mechanism is shifted to rotate the type-carrier or wheel H in one or the other direction. After the type-adjusting mechanism 90 and type wheel have been shifted in one or the other direction, they are restored to normal, central position and are held therein by oppositely-acting spring devices. The main spring-centering means is connected 95 through the shaft l^3 and comprises a depending arm 165 fixed to the shaft and two comparatively heavy, coiled springs 166 and 167 (see Fig. 12). These springs are connected to the lower end of the arm 165 100 and extend in opposite direction therefrom. The spring 166 is connected to a lug 168 on the plate 130 and the spring 167 is connected to an adjusting screw 169 threaded 105 through a lug 170 on the side-plate or bracket 130 and by means of which screw, the tension of the centering springs 166 and 167 are adjusted. In the normal, central position of the type-adjuster mechanism, the pull of the springs 166 and 167 110 thereon are counterbalanced but, as the type shifter mechanism is moved in one or the other direction, the tension of one or the other of these springs is increased and the amount to which it is increased is proportional 115 to the extent of shift of the type-adjusted mechanism and the type wheel rotated thereby so that, when the rotator magnet L or L' is deenergized, the spring centering device will act to quickly restore the 120 125 130

type-shifter mechanism and type wheel to its normal position. The time required to thus restore the type-adjuster mechanism and type wheel will be substantially the same whatever the extent of shift of the type wheel has been, since the greater the shift of the type wheel the greater the amount of tension placed upon one or other of the springs 166 and 167 and the greater effect it will have in restoring the type wheel.

While this spring-centering device acts to quickly restore the type wheel to central position and hold it therein, the effect of the two springs in central position is nearly counterbalanced and it would be extremely difficult to so adjust these springs as to accurately hold the type-adjuster mechanism and type wheel in center position. For this reason, a supplemental, more sensitive centering device is provided. In its preferred form, this centering device comprises two arms or disks 171 and 172 that are loosely mounted on the end of the shaft *l* that projects beyond the side-plate 130. A coiled watch spring 173 is arranged between the disks and is connected at its opposite ends to the hub of the disk 171 and to a pin 174 on the disk 172 near its outer edge. This spring tends to rotate the disks in opposite directions and holds the upwardly projecting lugs 175 thereon against the opposite sides of a fixed stop-pin 176 that projects from the side-plate 130. The arms 175 on the disk are also arranged to engage a laterally projecting pin 177 on the upper end of an arm 178 that is fixed to the shaft *l*. When the type-adjusting shaft *l* is rotated in one or the other direction, one or the other of the disks 171 or 172 is rotated against the tension of the spring 173 and, when the rotating magnet *L* or *L'* is deenergized, the spring 173 through the medium of the shifted disk and its lug 175 acts upon the pin 177 of the arm 178 to assist in restoring the shaft *l* and the type wheel geared thereto to central position. The restoring movement of the disk is arrested when its arm strikes the fixed stop-pin 177 and the restoring movement of the shaft *l* is arrested when the pin 177 on the crank-arm 178 engages the arm 175 of the other disk which has not been shifted. This centering device is of delicate construction and, while it assists in restoring the type wheel to centering position, it can not be readily employed for quickly restoring the type wheel after it has been rotated to a considerable extent. It does, however, act to accurately hold the type-shifter mechanism and type wheel in central position and thus supplements the action of the main centering springs 166 and 167. The two centering devices together act to quickly restore the type wheel whatever its extent of shift has been and to hold it in

central position ready for the next signal, as is of course desirable in order that rapidly transmitted signals can be received and the corresponding characters printed.

The extent of rotation of the type adjuster mechanism and type wheel is variably controlled by a set of selectors which are arranged to position a series of stops that engage and arrest a rotating arm connected to the type-adjuster mechanism. With the particular arrangement shown, there are four of these selectors that are controlled respectively by a set of four magnets which are responsive to the first four impulses of the signals or code permutations. The selectors position two stop devices and the fifth impulse of the signal or code permutation determines the direction of rotation of the type-adjuster mechanism against one or the other of the stops positioned by the selectors.

The stops are preferably in the form of a set of pins *m* and the selectors are in the form of a series of plates *n'*, *n²*, *n³* and *n⁴* having differently arranged holes 179 through which the stop pins *m* project into the path of movement of a stop-arm *M* on the type-adjusting shaft *l*. The pins are supported on a sliding carrier which comprises two circular plates or disks *m'* secured together at their upper and lower edges by screws 180 that are provided with spacing sleeves 181 between the plates. At the opposite side edges, the plates of the pin carrier are provided with projecting perforated lugs 182 having spacing sleeves 183 between them and which lugs and sleeves slidably engage two horizontal guide-rods 184. These guide-rods are fixed at their outer ends to the right-hand side plate 130 and project inwardly therefrom. At their inner ends, they are connected by a cross-bar 185. A fixed plate or disk 186 is provided with side lugs 187 engaging the guide rods 184 and fastened to the inner ends of spacing sleeves 188 which extend between the lugs and the right-hand side plate 130. The guide-rods or supports 184 are parallel with and arranged on opposite sides of the type-adjusting shaft *l*, so that the sliding pin-carrier is concentric with the shaft. The plates *m'* of the sliding pin-carrier and the fixed plate 186, and also the cross-bar 185 between the ends of the pins 184, are all provided with central openings through which the shaft *l* extends. The stop-pins *m* are arranged in two concentric rows about the shaft *l* (see Fig. 17), the pins in the rows being staggered, as shown. The pins are slidably mounted in suitable guide openings in the plates *m'* of the pin carrier, and a series of springs *m²*, coiled about the pins, extend between the inner plate *m'* and collars *m³* fixed to the outer ends of the pins, so that the pins are yieldingly held in normal posi-

tion with the collars m^3 engaging the right-hand plate m' . The pins are also arranged to slide through openings in the fixed plate 186 and, when the pin-carrier is shifted, the 5 different stop pins are arranged to project through the openings 179 of the selector plates n^1 , n^2 , n^3 and n^4 , in accordance with the setting of these plates.

The circular selector plates or disks (see 10 Figs. 16, 18, 19 and 20) are concentrically mounted upon the shaft l , one adjacent the other, and with the inner plate of the set abutting against the outer face of the fixed plate 186. The selector disks are arranged 15 to oscillate upon a collar 191 on the shaft and each of these plates is provided adjacent its lower edge with a segmental slot 192 through which extends a correspondingly shaped lug 193 that is fixed to the plate 186. 20 The slots are longer than the lug and the engagement of the ends of the slots with the ends of the lug limits the extent of oscillation of the selector plates. Each of 25 the selector plates is provided adjacent its lower edge with a lug having a laterally projecting pin 194 thereon and these pins engage slots in the upper ends of a set of arms n^5 that are mounted upon the right-hand end of a series of rock-shafts 195. 30 These shafts are journaled at their ends in upturned lugs 196 on brackets or plates 197 fixed to the bottom plate B, and a series of springs 198 are coiled about the left-hand ends of these shafts. Each spring is connected 35 at its opposite end to the corresponding shaft 195 and adjacent lug 196 and serve to hold the shaft and the selector disk in normal position and to restore them to normal after they have been shifted therefrom.

40 Each shaft 195 (see Fig. 16) is provided with an upwardly-projecting, extended arm 199 having an adjusting screw 200 threaded therethrough and held in place by a lock-nut 201. The heads of these screws are arranged 45 to be engaged by a series of actuator rods n^6 . These rods are arranged to slide through the stationary core-sections 202 of a series of four single-spool solenoid magnets N^1 , N^2 , N^3 and N^4 . The frames 203 of 50 these magnets are secured to the rear face of an upright plate or bracket 204 that is fixed to the base plate B, the magnets being arranged on the rear face of this plate and projecting rearwardly therefrom. The rear 55 ends of the actuator rods n^6 are connected to the movable core sections n^7 of these magnets, so that when any one of the magnets is energized, the actuator rod will shift the corresponding rock-shaft 195 and, 60 through the medium of the connector arm n^5 , move the corresponding selector disk from its normal to its shifted position. When the circuit through the selector actuating magnet N^1 , N^2 , N^3 and N^4 is broken, 65 the springs 198 on the shaft 195 will restore

the selector disks and the shifting devices therefor to normal position. The movement of each of the actuator rods n^6 and of the movable core sections n^7 connected thereto, is limited by a clip 205 fixed to the rear 70 end of the corresponding magnet and extending over the rear end of the movable core section.

The pin-carrier is shifted to project the pins m through the holes 179 of the selector 75 disks by an arm or lever m^4 (see Fig. 9), the upper, forked end of which engages a groove in a hub 207 on the face of the inner plate m' of the pin-shifter. The lower end of the lever is pivoted upon an inwardly-projecting stud 208. The outer end of this stud is fixed to a lug 209 that depends from a U-shaped bracket 210 (see Fig. 14) that is fixed to the right-hand side-plate 130 and projects inwardly therefrom. Intermediate its ends, the shifter arm m^4 is pivoted to the end of an actuator rod m^5 , the opposite end of which rod is adjustably threaded through a cross-bar 211 that is connected to the movable core sections 80 n^2 of a double spool solenoid magnet M' . The spools of this magnet are fixed at their right-hand ends to the inner face of the bracket 210 (see Fig. 14).

The signals in accordance with the present 85 system are transmitted by permutations of five impulses of opposite polarity. There are thirty-two of such permutations, twenty-seven of which are employed for printing characters, two for operating the capital and figure shift magnets H^1 and H^2 , one for 90 operating the line space magnet G^2 and two others for operating the carriage feed and carriage return mechanisms hereinafter set forth. The first four impulses of any code 95 signal or permutation control the set of selector actuating magnets N^1 , N^2 , N^3 and N^4 . In the present system, if the first impulse of any signal is negative, the magnet N^1 will be energized and the corresponding 100 selector plate or disk n^1 will be moved to its shifted position. If the first impulse is positive, the magnet N^1 will not be energized and the selector plate n^1 will remain 105 in normal position. If the second impulse is negative, the magnet N^2 will be energized and the selector plate n^2 moved to shifted position. If the second impulse is positive, the magnet N^2 will not be energized and the selector disk n^2 will remain in normal position. In a similar manner, the third and 110 fourth impulses of any signal determine whether or not the selector plates n^3 and n^4 will be shifted or remain in normal position. The fifth impulse of the signal completes 115 the operation of the receiver and, if a character is to be printed, determines which of the two rotating magnets L and L' will be energized in accordance as to whether the 120 fifth impulse is positive or negative, to 125 130

thereby rotate the type-adjusting mechanism and type wheel in one or the other direction.

There are sixteen different combinations into which the selector disks n^1 , n^2 , n^3 and n^4 can be arranged, but only fourteen of these are employed for printing characters. As shown, there are twenty-four of the stop-pins m (see Fig. 17). Twelve of these pins are arranged on one side of the normal central position of the stop-arm M and twelve on the opposite side. The openings 179 in the selector plates are differently arranged and in twelve of the different settings of the disks two series of openings therein will be in line to permit two of the stop-pins to be projected therethrough when the magnet M' is operated to shift the pin carrier. When the type-adjusting mechanism is rotated in one or the other direction by either of the magnets L L' , the stop-arm M , which is arranged adjacent the outer face of the outside selector plate, will engage one or the other of the pins and the type wheel will be arrested with the proper type opposite the printing point of the platen. It will be understood that in each of these twelve settings of the selector disks, the openings will be in line to admit a different pair of pins so that the pins are arranged to arrest the movement of the type wheel in twenty-four different positions. In two other settings of the disk, none of the pins will be projected therethrough and the type-adjusting mechanism and type wheel will be rotated in one or the other direction until the stop-arm M engages one or the other end of the projecting, segmental lug 193. The type wheel can thus be rotated to twenty-six different positions and, as a special combination or permanent mutation of impulses is arranged to operate the printing mechanism without moving the type wheel rotating mechanism, the normal, central position of the type wheel can be employed for printing characters and, as there are three rows of type, eighty-one characters in all can be printed.

After the proper type is brought opposite the printing point on the platen, the type wheel is shifted to strike the platen by an arm 212 (see Figs. 1 and 2) which is formed upon one of the collars 132 on the shaft 128 that rotates with the shaft but slides along the shaft with the carriage. This arm is connected by a link 213 to the rocking arm or frame j which carries the shaft 124 and the type wheel H . At its left-hand end, the shaft 128 is provided with a crank-arm p that is connected by a link p' to a rocking arm or lever p^2 pivoted on the inner face of the left-hand side-plate 130. The lever p^2 is pivoted intermediate its ends to the cross-bar p^3 which connects the movable cores P' of a double-spool solenoid magnet P . A spring 214 (see Fig. 10) is coiled about the right-hand end of the shaft 128 and is con-

nected at its ends to the shaft and to the right-hand side-bracket 130. This spring holds the striking mechanism in normal position with an adjustable stop-pin 215 on the inner end of the crank-arm p in engagement with a lug 216 on the inner face of the side-plate 130 (see Fig. 2). As soon as the selected type has been brought opposite the printing point, the striker magnet P is energized and rocks the shaft 128 to thereby oscillate the arm J and the type wheel H carried thereby to strike the selected type against the paper on the platen. When the magnet P is deenergized, the spring 214 on the shaft 128 restores the striker mechanism to normal.

As the type wheel is shifted to the platen, the type opposite the printing point is accurately centered by an arm 217 (see Figs. 1 and 2) which is pivoted to a lug 218 on the swinging arm or frame j . The upper end of this arm is arranged between the parts of a bifurcated or forked lug 219 on the upper end of the centering arm j and the extreme upper end of the arm is provided with a beveled edge which co-operates with the beveled teeth of a wheel 220 (see Fig. 3) which is fixed to the upper end of the shaft 124 and rotates with the type wheel. The lower end of the centering arm 217 is provided with a pin 221 (see Fig. 2) which engages a cam slot 222 in an upwardly projecting lug 223 on the carriage J . In the normal position of the type wheel shown in the drawings, the centering arm is held out of engagement with the toothed wheel 220 by the cam lug 223. As the type wheel is swung inwardly against the platen, the pin 221 moves through the cam slot 222 and the latter is shaped to throw the upper end of the centering device inwardly to engage the teeth of the wheel 220 and thereby accurately center the selected type before it strikes the platen.

A bent arm 224 is fixed to the carriage J and extends upwardly through the slot 159 of the top plate c' and then rearwardly beneath the platen (see Figs. 1 and 2). An arm 225 is connected by a pivot pin 226 to the rear end of the supporting arm 224 and the arm 225 extends forwardly from its pivot and thence upwardly and carries an inking roller 227 between the type wheel H and the platen G . The roller is journaled upon a horizontal pin 228 on the upper end of the arm 225 and is removably held in position thereon by a U-shaped spring 229. A spring coiled about the pivot pin 226 holds the arm 225 and inking roller 227 in normal position. As the type wheel swings in toward the platen, it strikes the inking roller, swings the arm 225 upwardly about its pivot pin 226 and against the tension of the spring thereon, so that the inking roller rolls over the selected type and moves up

out of the way so that the type can strike the platen. The arm 225 is provided with a lug 230 having a segmental slot therein which is engaged by a stop-pin 231 fixed to 5 the supporting arm 224.

The crank-arm *p* on the striker rock-shaft 128 is extended, as shown in Figs. 1 and 2, and is arranged to strike the end of a switch-arm *r* that is pivoted on a lug 232 on the 10 frame 233 of a magnet *R*. The frame of this magnet is secured to the base plate *B* and projects upwardly therefrom. The switch-arm *r* carries an insulated spring contact *r'* which is normally held into engagement with an insulated contact screw *r''* by a spring 234. The local operating circuit for the printer extends through this normally closed switch. Whenever the 15 striker mechanism is operated to print a selected letter, the arm *p* strikes the switch-arm *r* and disengages the contacts *r'* and *r''*, so that the operating circuit to the receiver is broken and the parts are restored to normal position and are ready to receive the 20 next signal.

The switch-arm *r* is also arranged to be shifted to disengage the contacts *r'* and *r''* by an actuating rod *r'* which extends through the core of the single spool solenoid 25 magnet *R* and is connected to the movable core section *R'* thereof. The actuator rod *r'* and the movable core section *R'* are normally upheld when the magnet *R* is deenergized by a clip 235 fixed to the lower end of the magnet frame and extending beneath the core section. Whenever any one of the five special signals are received which do not operate the type wheel, the magnet *R* is energized and the operating circuit is broken 40 thereby to permit the restoration of the parts to normal condition.

It should be noted that the type wheel *H* has a rotary and an axial movement to select the desired character and a movement bodily 45 of translation to print the selected type. It also shifts in letter-space direction with the carriage *J* to print the successive characters received and to form the spaces between words. To effect the letter-space feed of the 50 carriage, a cord 236 (see Fig. 9) is connected to a forwardly projecting lug 237 thereon and extends horizontally toward the right-hand end of the machine. At the right-hand end of the machine, a cord 236 passes 55 downwardly over a guide wheel 238 on the side-plate 130 and rearwardly over a second guide wheel 239 to a winding drum 240 (see Figs. 12, 13 and 14). This drum is journaled in a bracket 241 on the base plate *B* 60 and is provided with two ratchet wheels 242 and 243 that are arranged to be engaged respectively by the feeding and retaining pawls 244 and 245. The retaining pawl 245 is pivotally mounted on a lug 246 on the 65 base-plate of the bracket 241, and a spring

247 (see Fig. 14) coiled about its pivot normally holds it into engagement with the ratchet wheel 243. The feed-pawl 244 is pivotally mounted upon the end of an arm or lever 248 which is pivoted intermediate 70 its ends upon a lug 249 on the bracket 241, and is connected at its opposite end by a link 250 to a cross-bar 251 which connects the movable cores *S'* of a double-spool solenoid magnet *S* which is mounted on the bracket 75 241. A spring 252 extends between the tail of the feed pawl 244 and a lug 253 on the arm 248 and normally presses the feed-pawl into engagement with the ratchet wheel 242. A spring 254 extends between the arm 248 80 and the frame of a magnet *S'* on the bracket 241, and normally holds the arm 248 and feed-pawl 244 in position with the rear end of the arm 248 engaging an adjustable stop-pin 255 on the base of the bracket 241. 85

When the magnet *S* is energized, it draws up the rear end of the arm 248 and moves the feed-pawl 244 back idly over the teeth of the ratchet 242 and places the spring 254 under tension. When the magnet *S* is de- 90 energized, the spring 254 restores the parts and the pawl 244 then acts on the ratchet wheel 242 to advance the drum 240 and, through the medium of the cord 236, to advance the carriage *J* and type wheel *H* 95 mounted thereon one step in letter-space direction. The magnet *S* is energized whenever the striker operating magnet *P* is energized, so that the carriage *J* is advanced one step whenever the printing mechanism 100 is operated. The letter-space movement of the carriage, however, does not take place until after the circuit through the magnets *P* and *S* is broken. The transmission of a special signal is also arranged to operate 105 the letter-space magnet *S* without operating the printing mechanism to thereby form the spaces between the words.

The letter-space movement of the carriage is effected against the tension of a spring 110 drum 256 (see Fig. 9) journaled on the left-hand side-plate 130 and having a cord 257 wound thereon which extends over a guide pulley 258 upon the upper portion of the side-plate 130 and is connected to the lug 115 237 of the carriage. As the carriage is moved in letter-space direction, the cord 257 rotates the drum 256 and places its spring under tension so that, by releasing the feeding and retaining pawls 244 and 245 of the 120 winding drum 240, the spring drum 256 will act through the medium of the cord 257 to draw the carriage back to the left to commence a new line. The pawls 244 and 245 are disengaged from the ratchet 244 and 243 125 by an arm 259 that is pivoted on the lug 246 and is provided with a cross-pin 260 at its upper end which engages the upper ends of the feeding and retaining dogs or pawls. The arm 259 is provided with a tail-piece 130

- 261 which is arranged to be engaged by an actuator rod 262 which extends up through a single-spool solenoid magnet S^2 and is connected to the movable core S^3 thereof.
- 5 The rear end of an arm 263 is pivoted to the movable core S^3 . This arm is pivoted intermediate its ends upon a lug 264 on the brackets 241 and the forward end of the arm extends over a horizontal rod 265 that
- 10 extends transversely of the machine between the side plates 130. This rod is longitudinally movable through guide-openings in the plates 130 and is yieldingly pressed toward the right by a spring 266 (see Fig. 9) coiled around the rod and extending between the left-hand side-plate 130 and a collar 267 on the rod. At its right-hand the rod 265 is provided with a collar 268 which is normally pressed against the side
- 15 of the forward end of the arm 263.
- 10 The carriage return magnet S^2 is arranged to be energized by the transmission of a special signal. When this occurs, the actuator rod 262 is pushed downwardly to shift
- 20 the arm 259 and thereby disengage the feed and retaining pawls 244 and 245 from the winding drum 240. The spring drum 256 is then free to act to return the carriage to the left. The operation of the carriage return
- 25 magnet lifts the forward end of the arm 263, so that the rod 265 is shifted longitudinally to the right by its spring 266 and the collar 268 thereon is moved beneath the forward end of the arm 263 to lock the dog-releasing
- 30 mechanism and the feed and retaining dogs 244 and 245 in released position. The dogs are thus held in released position, even though the carriage return magnet S^2 is de-energized, and they are held in released po-
- 35 sition until the carriage is fully restored to the left-hand end of the machine to commence a new line. At the end of its movement to the left, a lug 269 (see Figs. 1 and
- 40 2) strikes the collar 267 on the rod 265 and
- 45 moves it longitudinally, to a slight extent, to the left against the tension of its spring 266, so that the collar 268 at its right-hand end is shifted from beneath the arm 263. The springs 247 and 252 of the dogs then
- 50 return them into engagement with the ratchets of the drum 240, so that the letter-space mechanism is again in condition to feed the carriage step-by-step in letter-space direction.
- 55 To prevent the overthrow of the winding drum 240 when the carriage is returned to the left, it is provided on its inner face with a stop-pin 270 which is arranged to be engaged by an arm 271 pivoted on a lug 272 on
- 60 the base-plate of the bracket 241. A second arm 273 connected to the arm 272 is also pivoted on the lug 272 and moves with the arm 271. A spring 274 coiled about the pivots of the arms 271 and 273, tends to press these
- 65 arms inwardly with the arm 273 against

the periphery of the drum 240. When the drum 240 is rotated in the direction indicated by the arrow in Fig. 12 to wind up the cord 236 and move the carriage in letter-space direction, the cord engages the arm 270 at the end of the arm 273 and moves it outwardly against the tension of the spring 274 and at the same time, moves the arm 271 out of the path of movement of the stop-pin 270. When the carriage is returned by the operation of the spring drum 256, the cord 236 is unwound from the drum 240 and moves from beneath the end of the arm 273, so that the stop-arm 271 is moved by the spring 274 back into position to engage the stop-pin 270 and arrest the rotation of the drum 240 and thereby prevent its overthrow. By preventing the overthrow of the drum 240 the cord 236 is held taut at the end of the return movement of the carriage and the feed mechanism is in condition at once to properly feed the carriage in letter-space direction.

The cross-bar 211 connected to the cores M^2 of the stop-pin shifting magnet M' , is arranged to engage a screw 275 that is adjustably threaded through the end of a switch-arm m^6 that is pivoted on a lug 276 on the face of the upright plate 204 (see Figs. 9 and 10). [This switch-arm carries a spring contact m^5 which is arranged to engage a contact screw m^8 on the lug 276. The switch-arm is spring-pressed to move the contacts into engagement, but the latter are normally held open by the engagement of the cross-bar 211 with the screw 275, but when the stop-pin operating magnet is energized, the cross-bar moves away from the screw and the contacts m^7 and m^8 are brought into engagement. These contacts are arranged in the energizing circuit of the type-adjusting or rotating magnets L and L' .

The first four impulses, as described, control the magnets N^1 , N^2 , N^3 and N^4 to set the selector plates n^1 , n^2 , n^3 and n^4 and the fifth impulse determines which of the two rotating magnets L or L' is to be energized, and also initiates the operation of the stop-pin shifter magnet M' to project the pins through the selecting plates or disks. When this magnet is energized, the contacts m^7 and m^8 are brought into engagement to close the operating circuit through one or the other of the rotator magnets L and L' , so that the type-adjusting mechanism is rotated in one or the other direction until the stop-arm M engages one of the projected pins. The operation of either rotator magnet also controls the closing of the circuit through the striker magnet P and the carriage feed magnet S , so that the type wheel is shifted to impress the selected type upon the paper on the platen and the operating circuit is broken by the separation of the

contacts r^1 r^2 by the arm p of the striker mechanism. The operating circuit to the parts of the receiver is broken and the magnets, including the magnet S , are deenergized, so that the line space feed mechanism is operated to advance the carriage one step and the type wheel and type wheel adjuster mechanism is returned to normal position in readiness to receive the next signal. 10 If a capital, figure or punctuation mark is to be transmitted, the operator will press one or the other of the special keys F or F' to transmit special signals and operate one or the other of the type wheel shifter magnets H' or H'' .

To permit the rapid operation of the receiver mechanism to print the successive characters, it is desirable to quickly and promptly arrest the type wheel and type adjuster mechanism when it is returned to normal, central position by the centering springs 166, 167 and 170. For this purpose, a stop is provided for engaging and arresting the return movement of the arm M on the type wheel adjusting shaft l . This stop is preferably in the form of a pin 277, see Figs. 9 and 10 which is arranged to slide longitudinally through an opening in the upper portion of the right-hand side-plate 130 and through an opening in a small bracket 278 fixed to the inner face of the side-plate. A spring 279 coiled about the pin extends between the face of the plate 130 and a collar 280 on the pin and tends 25 to press the pin inwardly. In the position shown in the drawings, the pin rests upon the outer face of the arm M , so that it does not interfere with the rotation of the type-adjusting mechanism in either direction but, as soon as the type-adjuster mechanism is rotated in one or the other direction, the stop-pin is pressed inwardly by its spring 279 and into the path of movement of the stop-arm M and the return of the stop-arm 30 is arrested by the pin. Before the type-adjuster mechanism is again rotated, the stop-pin is moved out of the path of the arm M by an outwardly projecting finger 281 on the upper portion of the outer plate m^1 of the stop-pin carrier. At the end of 35 the operation of the receiver, the stop-pin carrier, which has but a slight throw, is quickly restored to normal position by the springs m^3 on the pins m and the pin 277 is again projected into the path of movement of the arm M on the type-adjusting shaft, so that, although the type-adjusting mechanism and type wheel are spring-held in central position and arranged to move in opposite directions from normal, a dead stop is 40 provided for arresting the return movement of these parts. They are thereby arrested quickly and without vibrating, so that they are in readiness to quickly receive and press 45 the next succeeding character.

Instead of shifting the paper carriage step-by-step in letter-space direction to print the succeeding characters, as in the ordinary typewriter, the supports for the paper platen are stationary and the small, 70 light carriage J upon which the type wheel H is mounted, is shifted. This work must be done electrically and a smaller, quicker operating magnet can be employed for shifting the type wheel carriage than could 75 be used for shifting a heavy paper carriage. The speed of the machine is thereby increased by this arrangement. It should be noted that the shafts 128, 129 and 1 upon which the type wheel carriage slides, also 80 serve to effect the type-selecting and striking movements of the type-wheel. The mechanism and magnets arranged between the bottom and top plates B and B' is enclosed by a series of side-plates 282 secured 85 to the corner posts b .

The arrangement of transmitting and receiving or selecting circuits and relays, in certain respects, may be considered an improvement upon a prior electric telegraph 90 or selective system devised by us and set forth in an application for Letters Patent filed in the United States Patent Office January 22, 1908, Serial No. 412,094. Also the mode of operation of the present improved system, in certain other respects, is essentially different. Some of the features of the improved system by which it is adapted for use with the present improved transmitting and receiving apparatus were devised 100 jointly by us, but other broad features of improvement which are adapted to other forms of electric selective apparatus are the sole invention of Howard L. Krum and, while herein set forth in order that the present invention may be clearly understood, are reserved for the subject-matter of another application.

Fig. 21 is a diagram of the circuits, relays and magnets at one station. The set 110 of signal selecting or pole-changing switches D of the transmitter are connected respectively to a set of five line branches 1, 2, 3, 4 and 5 which are connected respectively to the normally disengaged or front 115 contacts of a set of five transmitting switches t arranged to be operated by a set of transmitting relays T^1 , T^2 , T^3 , T^4 and T^5 . The special selecting switch f^2 and its normally engaged or back contact are interposed as shown in the line branch 1. The normally engaged or back contacts of the selecting switches or pole-changers D are connected by conductors 6 to one pole (in the present instance, the positive pole) of 120 a divided battery 7 and the normally disengaged or front contacts of these switches, and also of the switch f^2 , are connected by conductors 8 to the other or negative pole of the divided battery 7. The cen- 125

130

ter of the divided line battery is connected to ground or to a suitable return wire. The selecting switches D are operated in different combinations, as described, by the keys of the transmitter through the medium of the cams d' to select the permutations that distinguish the separate characters or signals.

When the machine is used for transmitting, the line circuit extends from the transmitter switch t of the first transmitter magnet or relay T' through the several transmitter switches t in series. Each transmitter switch is connected to the normally engaged or back contact of the next switch in the series by a conductor 9. The last transmitter switch controlled by the relay T^5 is connected by a conductor 10 to the back contact of a normally closed unlocking switch t' which is arranged to be shifted to open position by a relay magnet t^2 . This switch is connected by a conductor 11 to one of the contacts of a manually shiftable switch r^4 . The other contact of the switch r^4 is connected by a conductor 12 to ground or to a return wire leading therefrom to a distant station. This switch is connected to one end of the main line wire or conductor 13 which extends therefrom through the oppositely wound coils 14 on a polarized relay R^2 and thence to the distant station. It will be understood that the opposite end of the main line wire or conductor 13 is similarly connected to the line relay R^2 and switch r^4 at the distant station. Each of the transmitting relays is arranged to operate a normally open switch t^3 which is arranged to control the circuit of the next succeeding magnet or relay of the set, each of these switches being connected to the coil of the next succeeding relay by a conductor 15, the conductor 15 from the switch t^3 of the last transmitter relay T^5 leading to the coil of the magnet or relay t^2 . The relay t^2 is arranged to control a normally closed unlocking switch t^4 , the normally engaged or back contact of which is connected by the conductor 16 to the front contact of the several switches t^3 and also to the first transmitter magnet T' and to the magnet E' . This latter magnet, as described, is arranged to complete the shift of any selected key and lock out the remaining keys until the selected key is restored to normal position. The front contact of the switch t^4 is connected by a conductor 17 to the coil of the magnet t^2 , and the switch is connected by a conductor 18 to the switches d and f^3 which are operated respectively by one of the cams d' and by the cam F^3 . Switches d and f^3 are normally open, the contacts thereof being connected by a conductor 19 to one pole of a local battery 20, the other pole of which is grounded or connected to a suitable return wire. Besides

the switches t and t^3 , the first transmitter relay T' operates a third switch t^5 which is connected to the local battery wire 19 and its normally disengaged contact is connected by conductors 21 and 18 to the unlocking switch t^4 of the magnet t^2 and to the normally disengaged contact of the switch t^3 of the last transmitter relay T^5 . The transmitter relays, the relay t^2 and the magnet E' are all connected on one side to ground or by a suitable return wire to the local battery 20. When the apparatus is used for transmitting, the switch r^4 will be positioned to connect the conductor 11 to the main line wire 13 at the transmitting station and at the receiving station, the corresponding switch will be employed to ground the main line wire or connect it to the divided line battery 7 by a suitable return wire. When any of the transmitting keys of the machine is depressed, except the special shift keys F and F' , one or more of the five impulse selecting or pole-changing switches D will be shifted and one or more of the five line branches, 1, 2, 3, 4 and 5 will be connected thereby to the negative side of the line battery 7, while the others remain connected to the positive side thereof and the switch d will also be shifted by any key, except the special shift keys F and F' to close the operating circuit from the local battery 20. Current will then flow from the local battery through the conductors 19, 18, unlocking switch t^4 , conductor 16 to the coils of the magnet E' and the first transmitter relay T' . The magnet E' will then be energized to complete the shift of the selected key and lock out the remaining keys. The operation of the first transmitter relay T' will shift its switch t^3 to closed position to thereby connect the second transmitter relay T^2 to the local battery through the conductor 16, switch t^3 and conductor 15. The second transmitter relay T^2 will then be energized and will in a similar manner operate its switch t^3 and connect the third transmitter relay T^3 to the local battery. The operation of this magnet will connect the fourth transmitter relay T^4 to the local battery and the latter will connect the fifth transmitter relay T^5 to the local battery. The operation of the magnet T^5 will shift its switch t^3 and will connect the magnet t^2 to the local battery from the conductors 18 and 21 to the switch t^3 and conductor 15 to the coil of the magnet t^2 . The operation of the magnet t^2 will shift the switch t^4 and thereby disconnect the conductors 18 and 16 and open the local operating circuit through the transmitter relays and through the magnet E' , so that the parts operated thereby are restored to normal condition. The transmitter relay magnets T^1 , T^2 , T^3 , T^4 and T^5 are thus successively connected to the local battery and are

operated in order, the circuit therethrough being opened at the end of their operation by the relay t^2 . This effects the successive operation of the transmitter switches t to 5 transmit the selected permutation or code signal by successively connecting the line branches 1, 2, 3, 4 and 5 to the line. When the switch t of the first transmitter magnet T' is shifted, current will flow from the 10 divided line battery 7 by the conductor 6 or 8 (in accordance as to whether or not the first pole-changing switch D has been shifted) to the first pole changing switch, thence by the conductor 1 through the 15 switch f^2 to the first transmitter switch t , through the transmitter switches t in order to the switch t' ; conductor 11, switch r^4 , conductor 13 through the coils 14 of the line relay R^2 at the transmitting station and 20 thence over the line to the line relay at the receiving station which is connected by the switch r^4 at the receiving station to the ground or to a suitable return wire leading back to the divided line battery 7. The 25 first impulse of the code signal or permutation is thus transmitted to the line and through the line relays R^2 at the transmitting and receiving stations and this first impulse will be positive or negative, in accordance as to whether or not the first selecting switch D has been shifted. The operation of the second transmitter relay T^2 will shift its transmitter switch t thereby disconnecting the first line branch 1 from 30 the line and connecting the second line branch 2 to the line and the second impulse, either positive or negative, in accordance with the position of the second selecting switch D , will be transmitted over the line. 35 Similarly, the successive operation of the transmitter relays, T^3 , T^4 and T^5 will disconnect the preceding line branch and interrupt the sending of the preceding impulse and connect the succeeding line branch 40 and effect the transmission of the succeeding impulse until all five impulses of the permutation have been transmitted, the transmission of the fifth impulse being interrupted by the operation of the magnet t^2 , 45 which shifts the switch t^1 and thereby disconnects the conductor 11 from the set of transmitting switches t . This relay, as stated, also shifts the switch t^4 to break the local operating circuit through the transmitting relays but the local operating circuit through its own coil is locked in closed condition by the switch t^4 , since, when it is shifted, current will flow from the power wire 18 through the switch t^4 and thence 50 by the conductor 17 through the coil of the relay t^2 . The circuit of the magnet t^2 remains in closed condition until the selected key is released to open the switch d and disconnect the conductor 18 from the local battery 20. The relay t^2 thus remains emer-

gized as long as the selected key is held depressed and the transmitting relays and the magnet E' are cut off from the local power circuit and also from the line and, although the operator may depress other 70 keys of the machine, no effect will be produced thereby until he releases the depressed key to open the circuit through the relay t^2 .

By means of this arrangement, it is impossible to overlap the signals in transmission by the too rapid operation of the keys. When any key is depressed, it initiates the operation of the transmitting relays and it is locked in depressed condition and the remaining keys are locked against operation by the lock-out magnet E^1 until the transmission of the selected permutation is completed. The magnet E^1 is then deenergized so that the universal shifting and lock-out 85 bar E (see Fig. 1) is restored to normal condition and the operator may then depress another key but he cannot transmit the succeeding signal until he releases the first key depressed, since it is necessary to do this to open the circuit of the magnet t^2 to thereby again permit of a connection between the transmitting relays and the local operating battery 20. The arrangement 90 permits the very rapid manipulation of the 95 keys without any confusion in the signals, since the operator can depress one key before he has entirely released the preceding key and the transmitter keys may thus be manipulated in much the same manner that 100 the keys of a typewriter are manipulated by a rapid operator, but it is impossible to have any of the succeeding signals overlapped upon the line circuit.

The switch t^3 at the last transmitter relay t^5 connects the conductor 18 to the coil of the magnet t^2 and its contact is not connected to the conductor 16, as are the other switches t^3 , for, if this were done, the magnet t^2 would be opening and closing its own 110 circuit and a buzzer like action would be produced.

When the shift-key F is depressed, the cams F^2 and F^3 are moved to momentarily move both of the switches f^2 and f^3 , and when this key is released the cam F^3 is operated to momentarily shift the switch f^3 . On the depression of the shift-key F' , the switch f^3 is momentarily shifted and when this key is released, both the switches f^2 and f^3 120 are momentarily shifted. The switch f^3 , like the switch d , connects the local battery 20 to the conductor 18 and thus initiates the successive operation of the transmitting relays T^1 , T^2 , T^3 , T^4 and T^5 , so that the line 125 branches 1, 2, 3, 4 and 5 are successively connected to the line as above described. Even though the switch f^3 is only momentarily shifted, the entire set of relays will operate, since the switch f^3 is necessarily 130

held shifted long enough to operate the first transmitter relay T^1 and this connects the conductor 16 directly to the local battery 20 and independently of the switch f^3 , 5 through the conductor 19, switch t^5 , conductor 21 and switch t^4 and the transmitter relays will operate in order whenever the switch f^3 is momentarily shifted. If the switch f^3 alone is shifted, the operation of 10 the transmitter relays will send a signal comprising five positive impulses over the line. If the switch f^2 is also shifted momentarily, the line branch 1 will be connected to the negative side of the divided line battery 7, while the transmitter relays T^1 and T^2 are operating and the first impulse of 15 the permutation will be negative while the remaining impulses will be all positive. When the shift-key F is thus depressed, a 20 permutation of impulses comprising one negative followed by four positive impulses will be transmitted over the line and when this key is released, a permutation comprising five positive impulses will be transmitted. 25 These same combinations will be transmitted in the reverse order when the shift-key F^2 is depressed and returned to normal position and these permutations, when transmitted in one or the other order, 30 are arranged at the receiver to shift the type mechanism to print either capitals or figures in accordance as to which of the permutations is first transmitted and, when the second permutation is transmitted to re- 35 store the type mechanism to print "lower case" letters.

The line conductor 13, as above stated, passes through the coils 14 of the line relays R^1 and R^2 , both at the transmitting and the receiving stations. The line relay controls 40 the receiving and printing mechanism, so that the message transmitted is printed both at the transmitting and the receiving stations. A branch of the battery wire 19 45 extends through opposed coils 22 of the line relay R^2 to the ground and these coils are preferably wound upon the same spools as the coils 14. A branch of the battery wire 19 is also connected to a normally 50 closed unlocking switch V , the contact of which is connected to a branched power wire 23. One of the branches of this conductor is connected to the tongue or armature r^2 of the line relay R^2 which is thus 55 connected to one side of the local battery 20 through the unlocking switch V . The circuit through the local coils 22 of the line relay are always closed during the operation of the apparatus. The armature r^2 is 60 normally held in central position between a pair of contacts 24 and the coils 22 balance one another and take the place of the permanent magnet ordinarily employed in a polarized relay. An impulse passing over 65 the line circuit and through the coils 14

will neutralize one of the coils 22 and will strengthen the other so that the armature r^2 will be shifted into engagement with one or the other of a pair of contacts 24 in accordance with the polarity of the line 70 impulse.

The conductor 23, which is connected to the local battery 20 through the normally closed unlocking switch V and the conductor 19, like the battery wire 19, is shown 75 in heavy lines in the diagram and is provided with a number of branches leading to different portions of the selecting apparatus. The armature r^2 of the line relay connects this operating circuit conductor to one or the other of a pair of conductors 25. The flow of current through the conductors 25 is arranged to selectively control a number of pairs of relays W^1 , W^2 , W^3 and W^4 and a relay W^5 . The first impulse of any 80 permutation will operate either one of the relays W^1 , in accordance with its polarity. The second impulse will operate one of the two relays W^2 . The third and fourth impulses of the permutation will operate one 85 of the relays W^3 and one of the relays W^4 and the fifth impulse, if its polarity is negative, will operate the relay W^5 . A series of transfer switches u^1 , u^2 , u^3 and u^4 , are arranged in pairs and are adapted to be operated by a set of relays U^1 , U^2 , U^3 and U^4 to successively connect the circuits of the selecting relays W^1 , W^2 , W^3 , W^4 and W^5 to the pair of conductors 25 as the impulses of a given permutation are received. The 90 switches u^1 of the first transfer relay U^1 are connected to the pair of main conductors 25. The switches u^2 of the second transfer relay U^2 are connected by a pair of conductors 26 to the front or normally disengaged contacts of the switches u^1 of the first transfer relay. In a similar way, the switches of the third and fourth transfer relays are connected to the front or normally disengaged contacts of the switches of the preceding 100 transfer relay in the set by pairs of conductors 26. A pair of branch conductors 31 and 31' lead from the back or normally engaged contacts of the first pair of transfer switches u^1 to the cores of the first pair of selecting relays W^1 , a normally closed switch w^1 being interposed in each of these branch conductors. The switch w^1 in the branch conductor 31 is operated by one of the pair of selecting relays W^1 and this 110 conductor leads to the other relay W^1 and the switch w^1 , interposed in the branch conductors 31' is operated by the second relay W^1 of the pair and leads to the core of the first relay of the pair. The operation of either of the pair of selecting relays W^1 will 115 cut out the other selecting relay w^1 of the first pair so that it cannot be operated. In a similar manner, the coils of the second pair of selecting relays W^2 are connected 120

125

130

to the back contacts of the transfer switches u^2 by a pair of branch conductors 32 and 32' and the third and fourth pairs of selecting relays W^3 and W^4 are connected to the back contacts of the transfer switches u^3 and u^4 respectively by pairs of branch conductors 33 and 33' and 34 and 34'. Each selecting relay is arranged to open a normally closed switch w^1 in the circuit of the other relay of the same pair, so that when any one of the relays is operated, the circuit of the other relay of the same pair is opened by the switch w^1 in its circuit. A fifth pair of branch conductors 35 and 35' are connected to the front contacts of the fourth pair of transfer switches u^4 .

Each of the selecting relays W^1 , W^2 , W^3 and W^4 is arranged to operate a pair of locking switches w^2 and w^3 that are connected to branches of the battery wire 23 that, as stated, lead from the battery 20 through the conductor 19 and the normally closed unlocking switch V. The contacts of the switches w^2 are connected to the coils of the respective relays so that, when any one of these relays is energized, the circuit to the local battery 20, will be closed through its coil and held in closed condition by the operation of the corresponding locking switch w^2 . The switches w^3 of each pair of selecting relays are connected by conductors 36 to the coil of the corresponding transfer switch relay. Thus when either of the pairs of selecting relays w^1 is operated, the corresponding transfer switch U' will also be operated and the circuit of the local battery through its coil will be held in closed condition so long as either one of the relays W^2 remains energized. In a similar manner, the operation of either one of the pair of selecting magnets W^2 will energize the second transfer switch relay U^2 and the operation of either of the pairs of magnets W^3 or W^4 will operate the corresponding transfer switch relays U^3 and U^4 . The branch conductors 31, 32, 33 and 34 are provided with extensions 31'', 32'', 33'' and 34'' which lead to the contacts of a set of switches X that are operated by a relay X^1 . The two branch conductors 35 and 35' lead to the contacts of the two remaining switches of this set. As stated, each signal or character is represented by a permutation of five impulses of opposite polarity. The first line impulse will energize the line relay R^2 and shift its armature in one or the other direction, so that the circuit from the local battery 20 may be traced therefrom by the conductor 19, normally closed unlocking switch V, battery wire 23 to the line relay armature r^2 and thence by one or the other of the main conductors 25 to one or the other of the switches u^1 of the first transfer switch relay U^1 and thence by one or the other of the branch conductors 31

or 31' through the switches w^1 therein to the coil of one or the other of the first pair of selecting relays W^1 and then back to the local battery 20 through the ground or by means of a suitable return wire. It will be understood that the selecting relays W^1 , W^2 , W^3 and W^4 and the set of transfer switch relays U^1 , U^2 , U^3 and U^4 are all connected to ground or by a suitable return wire to the local battery 20. If the first line impulse is positive, the selecting relay W^1 interposed in the branch conductor 31' will be energized and if negative, the selecting relay W^1 in the branch conductor 31 will be energized and this branch conductor, together with the extension 31'' thereof will be locked in closed condition at this point. That is to say, the operation of either of the pair of selecting relays W^1 will shift the corresponding set of switches w^1 , w^2 and w^3 . The operation of the switch w^1 will cut out the other selecting relay of the pair and the operation of the switch w^2 will close the locking circuit from one of the branches of the battery wire 23 through the coil of the selected one of the first pair of relays and it will be held closed independently of the further operation of the line relay R^2 . The operation of the switch w^3 of either of the first pair of selecting relays W^1 , will close the local battery circuit through the first transfer switch relay U^1 by connecting the battery wire 23 to the coil of the relay U^1 through the conductor 36. The first transfer switch relay U^1 will then operate, disconnect the first pair of branch conductors 31 and 31' from the main conductor 25 and connect the second pair of branch conductors 32 and 32' thereto through the medium of the second pair of transfer switches U^2 and the conductors 26 that are connected to the normally disengaged front contacts of the switches u^1 of the first transfer switch relay U^1 .

The second line impulse of the permutations passing through the coils 14 of the line relay R^2 will shift the armature r^2 thereof in one or the other direction and will close the local operating circuit from the battery wire 23 and armature r^2 to one or the other of the main conductors 25 to the switches u^1 of the first transfer relay U^1 , thence by the conductors 26 to the pair of switches u^2 of the second transfer relay and thence either by the branch conductor 32 or the branch conductor 32' to one or the other of the second pair of selecting and locking relays W^2 . The second line impulse of the permutation will then select one or the other of the branch conductors 32 or 32' and will close the local operating circuit through one or the other of the second pair of the selecting relays W^2 . The operation of either of these pair of relays will disconnect the second pair of branch

conductors 32 and 32' from the main conductors 25 and will connect the third pair of branch conductors 33 and 33' thereto, so that the third impulse of the set will operate 5 either one of the two magnets W^3 and lock the circuit of the selected magnet in closed condition and the fourth impulse of the permutation will select one or the other of the pair of relays W^4 and lock its circuit in 10 closed condition. The fifth impulse of the permutation will select one or the other of the branch conductors 35 or 35'. In this way, the selecting magnets W^1 , W^2 , W^3 , W^4 will connect one or more of the extension 15 conductors 31'', 32'', 33'' and 34'' of the branch conductors 31, 32, 33 and 34 to the local battery 20 through the selector unlocking switch V and the flow of current through these extension conductors and 20 through the branch conductors 35 and 35' is arranged to control the printing mechanism as hereinafter set forth.

In the system set forth in our prior application No. 412,094 above referred to, 25 there were ten relays in the transmitting set, the first being arranged to connect the first line branch to the line, the second to disconnect it therefrom, the third connecting the second line branch to the line, the fourth 30 disconnecting the second branch, and so on, so that the permutations of any given signal were transmitted with appreciable pauses or interruptions of the main line circuit. In that system, the transfer switches at the 35 receiver which successively connected the pairs of branch circuits and of locking and selecting relays therein to the main conductors controlled by the line battery, operated at the pauses or interruptions of the main 40 line circuit between the separate impulses of the permutation. The second transmitting relay T^2 in the system here shown, not only disconnects the first line branch 1, but connects the second line branch 2 thereto 45 and the third relay T^3 disconnects the second line branch 2 and connects the third line branch 3 thereto and so on, so that the impulses of any given permutation follow one another with great rapidity and with 50 practically no, or only very slight, interruptions in the line circuit. At least, the effect of the inductive capacity of the line and the magnetic lag of the line relays is such that the slight interruptions in the line 55 circuit between the successive impulses does not affect the line relay and its armature is not moved when the transmission of any given permutation is commenced unless the current in the line circuit is reversed, as 60 when a negative impulse follows a positive, or vice versa. It follows from this that two succeeding impulses of the same polarity at the receiver form in effect one long impulse of double length and three impulses, a long 65 impulse of three times the length of an ordi-

nary impulse. It follows that the selecting relays must be variably responsive to different lengths of impulses and be independent of any interruptions in the line circuit between the impulses of like polarity in any 70 given signal.

The transfer switch relays in the present system, instead of acting at the pauses between the impulses of the permutation as in the prior system referred to, operate as 75 above described, as soon as either one of the corresponding pair of selecting magnets is energized and the speed of operation of the selecting and transfer switch relay magnet is tuned to correspond with the speed 80 of operation of the transmitting relays.

The first impulse of a permutation is sent to the line as soon as the first transmitting relay T^1 is energized. At the same time, the circuit of the second transmitting relay T^2 is 85 connected to the local battery and the length of the first impulse depends upon the time required for the second relay T^2 to operate. In the same way, the length of the succeeding impulses in the permutations depend upon 90 the length of time it requires the succeeding transmitting relays to operate. These transmitting relays are relatively slow acting, so that heavy, strong impulses may be impressed upon the line circuit. The selecting 95 relays W^1 , W^2 , W^3 and W^4 of the receiver are very sensitive, quick-acting magnets so that they will quickly respond to the operation of the line relay R^2 . The transfer switch relays U^1 , U^2 , U^3 and U^4 which are 100 operated from the local battery through the medium of the selecting relays, are relatively slow-acting. The timing of the transfer switch and selecting relays is such that, the time required for one of the first pair 105 of selecting relays W^1 and the first transmitting switch relay U^1 to operate is the same as required by the second transmitting relay T^2 to operate. The time required to operate one of the second pair of selecting 110 relays W^2 and the second switch relay U^2 is the same as is required by the transmitting relay T^3 . In a similar manner, the time of operation of one of the third set of 115 selecting relays W^3 and the transmitting switch relay U^3 and of one of the selecting relays W^4 and the transfer switch relay U^4 correspond respectively to the time of operation of the transmitting relays T^4 and T^5 . By reason of this arrangement, it is not 120 necessary to interrupt the line circuit between the impulses of like polarity in any given permutation. For example, if the first two impulses of any permutation are of the same polarity to give in effect one impulse 125 of double length, it will first, as described, operate one of the pair of selecting relays W^1 and the transfer relay U^1 and then properly operate one of the selecting relays W^2 and the transfer switch relay U^2 . If 130

this double impulse is positive, the branch conductors 31' and 32' will be selected and if negative, the branch conductors 31 and 32 and the extensions 31'' and 32'' will be selected. If the first three impulses of the permutation are of the same polarity thereby forming in effect at the receiver one long impulse of three times the length of an ordinary impulse, one of the third pair of selecting relays W^3 will be operated and the third transfer relay U^3 and one or the other of the branch conductors 33 or 33' will be selected. Impulses of like polarity in any given permutation may thus follow one another without any appreciable interruption of the line circuit. At least without sufficient interruption in the line circuit to cause the line relay armature to drop away from one of the contacts 24 and the set of selecting relays will variably respond to the varying lengths of impulses formed by crowding together the impulses of the permutation and the only changes necessary, after the transmitting of the permutation is once initiated, are reversals of the line circuit where an impulse of one polarity follows that of the other. In this way, the transmission of the succeeding impulses of any permutation may be effected very rapidly and is not affected by the inductive capacity of the line or the magnetic lag of the line relays, since reversals on the line will quickly overcome the lag due to either of these causes.

It is not necessary that the synchronous operation or tuning of the selecting and transmitting relays be absolutely accurate. The selecting relays operate much more rapidly than the transmitting relays and it is only necessary, for example, that one of the magnets W^1 operate at some portion of the time that the transmitting relay T^1 is acting, and so on with the corresponding selecting relays and transmitting relays. When an impulse of negative polarity follows an impulse of positive polarity, or vice versa, in a permutation, it is not necessary that this reversal shall occur in absolute synchronism with the operation of the corresponding transfer relay since, when one of a pair of selecting relays is operated, it cuts out, by means of its switch w^1 the other relay of the same pair. For example, if a permutation commences with a positive impulse followed by a negative impulse, the positive impulse will operate the selecting relay W^1 in the branch conductor 31' and will cut out the relay W^1 in the branch conductor 31 which responds to negative impulses by means of the switch w^1 . Then, if the line reversal occurs before the transfer switch U^1 has completed its operation, it cannot affect the negatively responsive selecting relay W^1 and it is only necessary that this second impulse shall be prolonged

sufficiently to select the negatively responsive relay W^2 of the second pair and thereby connect the branch conductor 32 and its extension 32'' to the local battery.

This arrangement not only permits the impulses of any given permutation to follow one another very rapidly and thereby increases the speed of transmission of the messages, but it also obviates the difficulties here-
tofore encountered in electric selective sys-
tems due to the lag of the line circuit which
varies with the length and capacity of the
line, the weather conditions and the ad-
justment of the line relays. As explained
above, this synchrony in the operation of the
selecting and transmitting relays need not
be absolutely perfect. Moreover, inasmuch
as the transmitting and selecting relays are
restored to normal condition at the end of
any complete permutation or code signal, the
two sets of relays start in perfect synchrony
at the beginning of each permutation.

This timing or tuning of the selecting or receiving apparatus to correspond with the time of transmission of the impulses of per-
mutations or code combinations, so that the
receiver will variably respond to different
lengths of impulses, and so that it is not
necessary to interrupt the line circuit be-
tween successive impulses of the same po-
larity, is the sole invention of Howard L.
Krum and, while herein set forth to fully
explain the operation of the present im-
proved transmitting and selective printing
apparatus, it can be employed with different
forms of transmitting and selective appa-
ratus and is set forth and claimed on an ap-
plication filed by Howard L. Krum, May
29, 1910, Serial No. 464,120.

The four conductors 31'', 32'', 33'' and 34'' which, as above described, are variably selected by the first four impulses of any permutation, are connected to the contacts of the four sets of switches X. These four switches are connected by a set of four con-
ductors 36 to the four selector operating
magnets N^1 , N^2 , N^3 and N^4 which control
the selector disks or plates n^1 , n^2 , n^3 and n^4 .
These magnets are also connected to ground
or by a suitable return wire to the local bat-
tery 20, so that the variable operation of the
selecting and locking relays W^1 , W^2 , W^3 and
 W^4 will variably select these operating mag-
nets to effect the different settings of the
type-selecting disks. These selector operat-
ing magnets are arranged to operate nor-
mally open locking switches n^8 which are
connected to the coils of respective magnets
and the contacts of which are connected to
a branched conductor 37, shown in heavy
lines in the diagram, and which connect dif-
ferent parts of the printing apparatus to the
local battery 20 through the normally closed
unlocking switch r' and one of the branches
of the battery wire 19. This switch, as pre-
130

viously described is arranged to be opened by the arm p of the striker mechanism and also by the relay or magnet R . When any one of the set of operating magnets N^1 , N^2 , N^3 and N^4 is selected and energized, its circuit will be locked in closed condition from the battery 20 through the wire 19, unlocking switch r' conductor 37, switch n^8 of the selected magnet to the coil thereof and thence by the ground or by a suitable return wire to the local battery 20. These operating magnets will thus variably respond to the first four impulses of any permutation and they will respond to impulses of only one polarity; that is to say, if the negative impulses are employed to select the branch conductors 31, 32, 33 and 34 and the extension conductors 31'', 32'', 33'' and 34'' thereof, the operated magnets will be energized or not, in accordance with the varied permutations of the positive and negative impulses that represent the different signals and characters. That is to say, if the first impulse of any permutation is negative, the first operating magnet N^1 will be energized and the selector plate n^1 will be moved to its shifted position. If the first impulse of the permutation is positive, the magnet N^1 will not be energized and the selector plate n^1 will remain in normal position. Similarly, the other operating magnets N^2 , N^3 and N^4 will be energized or will remain in normal condition and the selector plates n^2 , n^3 and n^4 will be moved to shifted position or remain in normal position, in accordance with the polarity of the second, third and fourth impulses of the permutation.

The selector operating magnets N^1 , N^2 , N^3 and N^4 not only variably set the selector disks, but they also control a contracted fan circuit to select any one of a series of conductors 41, 42, 43 and 44 through the medium of a set of switches y^1 , y^2 , y^3 , y^4 and y^5 . The switch y^1 is controlled by the magnet N^3 and is connected by a conductor 38 to the switch-arm m^7 that is arranged to be brought into engagement with its contact m^8 by the operation of pin shifter magnet M' , as previously described. The switch y^2 is operated by the magnet N^2 and is connected to the back contact of the switch y^1 by a conductor 39. The switch y^3 is operated by the magnet N^4 and is connected to the back contact of the switch y^2 by a conductor 40. The switch y^4 is operated by the magnet N^4 and is connected by a conductor 45 to the back contact of the switch y^3 . The switch y^5 is also operated by the magnet N^4 and is connected by a conductor 46 to the front contact of the switch y^4 . The conductor 41 is connected to the front contact of the switches y^1 , y^2 and y^5 . The conductor 42 is connected to the back contact of the switch y^5 . The conductors 43 and 44 are connected to the front and back contacts respectively of the switch y^4 . The arrangement is such that the different operations of the magnets N^1 , N^2 , N^3 and N^4 will connect the conductor 38 to any one of the conductors 41, 42, 43 or 44.

The fifth impulse of any permutation selects, as stated, either one of the branch conductors 35 or 35'. These conductors are connected respectively to the normally engaged contacts of two switches x' and x^2 which, together with the switches X are operated by the magnet X^1 . The switch x' is connected by a conductor 47 through a normally closed switch w^6 and a conductor 48 to the coil of a selecting relay W^5 which is thus energized whenever the fifth impulse is negative and selects conductor 35'. The switch x^2 is connected by a conductor 49 through the coil of the magnet M' which operates the stop-pin carrier. The other pole of this coil is connected to the ground or by a suitable return wire to the local battery 20. The switch x^2 is also connected to the coil of the magnet X^1 , the other side of which is grounded or connected by return wire to the local battery 20, so that this magnet is energized when the fifth impulse of a permutation is positive and closes the circuit through the branch conductor 35. The operation of this magnet shifts the switches X , x' and x^2 . The switch x^2 is provided with a front or normally disengaged contact which is connected to the local battery 20 through the battery wire 19, normally closed unlocking switch r' and one of the branches of the conductor 37, so that when the magnet X^1 is operated, the local battery circuit is closed therethrough by the movement of the switch x^2 into engagement with its front contact. This shift of the switch x^2 also closes the local battery circuit through the magnet M' and this circuit is held closed through the magnet X^1 and M' until opened by the disengagement of the unlocking switch contacts r' and r'' .

The relay W^5 which is energized when the fifth impulse of any permutation is negative, is arranged to shift the switch w^6 and thereby disconnect its coil from the conductor 47 and also to shift a lock switch w^5 , the normally disengaged contact of which is connected by the conductor 37 to the normally closed unlocking switch r' and conductor 19 to the local battery, so that, when this relay is energized, current will flow from the battery through the conductor 19, switch r' , conductor 37, switch w^5 and conductor 48 through the coil of the magnet W^5 and back to the local battery through the ground or by a return wire. The shift of the switches w^5 and w^6 also serves to close a circuit from the battery through the conductor 19, switch r' , conductor 37, switches w^5 and w^6 to a conductor 51, thence to the coil of the relay X^1 and also by a conductor 130

49 to the coil of the magnet M^1 and back from the coils of these magnets through the ground or by a return-wire to the local battery 20.

5 The first four impulses of any permutation serve to select one or more of the branch conductors 31, 32, 33 and 34 and corresponding extensions 31'', 32'', 33'' and 34'' thereof and the selected branches will be 10 locked in connection with the local battery by means of the locking switches w^2 of the corresponding relays W^1 , W^2 , W^3 and W^4 . These locking switches connect the selected branch conductors to the local battery, as 15 stated, through the normally closed unlocking switch V , so that the selected relays will remain energized independently of the line relay and until the unlocking switch V is opened. At the same time, if the magnet 20 X^1 is deenergized and the switches X are in engagement with their contacts, the set of magnets N^1 , N^2 , N^3 and N^4 will be variably operated and the circuit of any one or more of these magnets which is closed 25 will be locked in closed condition by the operation of the switches n^8 . These switches, as stated, serve to close the local battery circuit through the selected magnets N^1 , N^2 , etc., from the conductor 37 that 30 leads from the normally closed, unlocking switch r^1 , so that, when these magnets have been properly operated, they will remain in operated condition independently of the line relay and also independently of the selecting and locking magnets W^1 , W^2 , W^3 and W^4 until the switch r^1 is opened either 35 by the operation of the striker magnet P or of the releasing magnet R . The fifth impulse, as stated, whether positive or negative, operates the magnets X^1 and the pin shifting-magnet M^1 and the local battery circuit is closed through the coils of these magnets by the switch r^2 . If the fifth impulse is negative, the relay W^5 will also be 40 energized and if operated, its circuit will be locked in closed condition by the switch w^5 . The locking switches n^8 , w^2 and w^5 connect the coils of the magnets N^1 , N^2 , N^3 , N^4 , X^1 , M^1 and W^5 to the local battery 45 50 through the unlocking switch r' and conductor 37, so that these magnets, when operated, will remain in operated condition independently of the line relay and of the selecting magnets W^1 , W^2 , W^3 and W^4 until 55 the unlocking switch r^1 is operated. The operation of the magnet X^1 by the fifth impulse of any permutation closes a circuit from the local battery 20 through the battery wire 19, switch r^1 , conductor 37, switch w^2 to the conductor 51 and thence by a conductor 52 to a normally open switch u^5 which is operated by the fourth transfer switch relay U^4 . At this time, the transfer relay U^4 is energized (as it must be, in order 60 65 that the fifth impulse be transmitted to the

relay or magnet X^1) and the circuit is further traced from the switch u^5 through a conductor 54 through the coil of the unlocking switch magnet V' and back to the local battery through the ground or by a return wire. The unlocking switch V is then opened to thereby disconnect the conductor 23 from the local battery, so that all the selecting and locking magnets W^1 , W^2 , W^3 and W^4 return to normal condition and 70 are ready to receive the next signal or permutation. The unlocking switch V will also return to normal condition, since the circuit through the coil of the operating magnet V^1 is opened when the fourth pair of 75 selecting and locking relays W^4 and the corresponding transfer switch relays U^4 are deenergized. The selector operating magnets N^1 , N^2 , N^3 and N^4 , the relay W^5 (if operated), the relay X^1 and the pin-shifting magnet M^1 will remain energized, since they are connected to the local battery through the unlocking switch r' .

The operation of the magnet M^1 will shift the pin carrier to project two of the pins 90 m through the selector plates n^1 , n^2 , n^3 and n^4 in accordance with the setting of these plates, as previously described. At the same time, the switch contacts m^7 and m^8 will be placed in engagement and a circuit will be 95 closed from the local battery 20, conductor 19, unlocking switch r^1 , battery wire 37, switch w^2 of the magnet X^1 , conductors 49 and 50, contacts m^8 and m^7 to conductor 38, thence through the set of switches y^1 , y^2 , y^3 , y^4 and y^5 to one or the other of the set of 100 conductors 41, 42, 43 and 44, in accordance with the varied operation of the magnets N^1 , N^2 , N^3 and N^4 . The conductor 41 is connected to a switch y^6 controlled by the 105 magnet W^5 , and if a character is to be printed, the circuit will be closed through this conductor and it may be further traced from the switch y^6 to one or the other of a pair of conductors 55 and 56 in accordance 110 with the polarity of the last impulse of the permutation which operates relay W^5 only if it is negative. Thence the circuit is traced to one or the other of the rotating magnets L or L' and thence from either of these magnets by a common conductor 57 to the coil of a relay L^3 and thence through the ground or by a return wire to the local battery 20. One or the other of the rotating magnets L or L' will be operated to rotate the type 115 adjusting shaft l in one or the other direction until the stop-arm M engages one or the other of the projected stop pins m . The selected type on the type wheel H is thus brought opposite the printing point of the 120 platen. At the same time, the circuit of the relay L^3 is closed and the operation of this relay will shift two switches l^6 and l^7 and a circuit will be closed from local battery 20 by the conductor 19, unlocking switch r^1 , 130

battery wire 37 to the switch l' , thence by a conductor 58 through the coil of the letter-space magnet S to a conductor 59, switch l'' and by a conductor 60 to the coil of the 5 striker magnet P and thence through the ground or by a return wire back to the local battery 20. The striker magnet will thereby be energized to bring the type-wheel H and impress the selected type on the paper 10 on the platen and the arm p will be shifted to open the switch contacts r' and r'' and thereby disconnect the power wire 37 of the local battery so that all parts of the printing apparatus will be returned to normal 15 condition in readiness to print the next signal. The operation of the magnet S as stated, places the letter-space feed mechanism in condition to advance the carriage and the type wheel one step in letter-space 20 direction when the circuit through the magnet is broken.

It should be noted that the magnets of the printing apparatus are energized in succession to operate the parts of the printer in proper order. That is to say, the first four 25 impulses of the signal variably control the magnets N^1 , N^2 , N^3 and N^4 to set the selector disks and the fifth impulse energizes the magnet M^1 to shift the stop pins m . The 30 operation of this magnet closes the local circuit through one of the rotating magnets L or L' to move the type-adjuster until the stop-arm M engages one of the pins m . The 35 relay L^3 operates simultaneously with one of the rotating magnets and the local circuit is then closed thereby simultaneously through the striking magnet P and the letter-space magnet S to bring the selected type to the printing point and place the carriage feed mechanism in condition to advance the 40 carriage carrying the type wheel H when the operating circuit of the printing apparatus is broken by the unlocking switch r' .

The fifth impulse of any permutation, 45 whether positive or negative, operates the magnet X^1 and thereby disconnects the printer operating circuits from the selecting circuits and at the same time, the magnet or relay V' is energized to open the unlocking 50 switch V, so that the selected circuits are restored to normal condition. The selected circuits of the printing mechanism, however, are not broken, since they are locked in connection with the local battery through 55 the unlocking switch r' . It is obvious, therefore, that as soon as the fifth impulse of any permutation is received, the selecting circuits and magnets W^1 , W^2 , W^3 , and W^4 are in condition to receive the next succeeding 60 signal or permutation while the printing apparatus is operated to print the character corresponding to the prior signal. At least, the first four impulses of the next succeeding permutation can be received to varying 65 ably operate their magnets W^1 , W^2 , W^3 and

W^4 and thereby selectively connect the conductors 31'', 32'', 33'' and 34'' to the local battery, and it is only necessary that the unlocking switch r' shall be opened to break the circuit through the magnet X^1 and permit the switches w' and w'' to drop back into engagement with their contacts before the fifth and last impulse of the next succeeding signal is received. In other words, the selection of the next succeeding signal may be 75 initiated or built up while the character corresponding to the signal just received is being printed. When the operation of the printing apparatus is completed, the switch r' is opened and the magnet X^1 is deenergized, so that the switches controlled thereby by drop back into engagement with their contacts. The set of operating magnets N^1 , N^2 , N^3 and N^4 will then be properly operated 80 in accordance with the signal which has been built up by the selective operation of the magnets W^1 , W^2 , W^3 and W^4 and the switches w' and w'' will be in proper position to receive the fifth impulse that selects one or the other of the two branch conductors 85 35 or 35' and the printing apparatus will be operated as before, to print the character corresponding to the signal. In the preferred arrangement shown, the unlocking switch V opens the locking circuit through 90 the selecting and locking magnets W^1 , W^2 , W^3 and W^4 which are variably responsive to the first four impulses of any permutation. This switch being preferably operated as described as soon as the fifth impulse of 95 a permutation is received. This switch, however, does not open the locking circuit through the selecting and locking magnet W^5 which is variably controlled by the fifth impulse of the permutation. The circuit 100 of this magnet when energized is closed through the locking switch r' , and this locking circuit is not opened until the operation of the printing mechanism is completed. As 105 the magnets which operate the printing apparatus, particularly the rotating magnets L and L' , the striking magnet P and the letter-space magnet S are necessarily strong magnets and somewhat slow in operation, this separation of the selecting and operating circuits, by what may be termed the dividing magnet X^1 , greatly increases the speed at which the signals may be received and the corresponding characters recorded. 110

As above stated, the fan circuit controlled 115 by the switches y^1 , y^2 , y^3 , y^4 and y^5 that are variably operated by the magnets N^1 , N^2 , N^3 and N^4 is arranged to connect any one of the conductors 41, 42, 43 and 44 to the conductor 38, so that the local battery is connected to the selected conductor when the contacts m^7 and m^8 are brought into engagement by the operation of the pin-shifter magnet M^1 . Twenty-six of the thirty-two 120 permutations select the conductor 41, which 125 130

leads to the switch y^6 of the magnet W^5 , and which controls the conductors 55 and 56 leading to the rotating magnets L and L' . In half of these twenty-six permutations, 5 the fifth impulse will be positive and the magnet W^5 will not be energized and in half the fifth impulse will be negative to thereby operate the magnet W^5 and move the switches controlled thereby. Half of 10 these twenty-six permutations will thus energize the magnet L to rotate the type-adjusting mechanism in one direction and the other half will energize the magnet L' to rotate the type-adjusting mechanism in 15 the opposite direction.

The conductors 42, 43 and 44 lead to a set of switches y^7 , y^8 and y^9 which are also operated by the magnet W^5 and control a set of six conductors 61, 62, 63, 64, 65 and 20 66 which are connected to the back and front contacts thereof. Six special permutations will thus variably operate the magnets N^1 , N^2 , N^3 and N^4 and the magnet W^5 to select any one of these six conductors.

25 If the conductor 63 is selected, the circuit will be closed through a resistance coil R^3 to the conductor, 57 and thence through the relay L^3 to the ground. This last relay will then operate as before, to close the circuit 30 through the letter-space magnet S and the striker magnet P . But, inasmuch as the circuit has not been closed through either of the rotating magnets L or L' , the center letter on the type-wheel will strike against 35 the paper on the platen.

If the conductor 64 is selected, the circuit will be closed therethrough to the carriage feed magnet S , thence by the conductor 59 to the switch b^6 to a conductor 67 and 40 through a resistance coil R^4 and a conductor 68 to the releasing magnet R and thence to the ground or back by a return wire to the local battery 20. The letter-space feed magnet will be alone operated and the parts of 45 the printing apparatus restored to normal, to form the spaces between the words.

If the conductor 61 is selected, the circuit will be closed therethrough and through the line space magnet G^2 to conductors 69 and 68 50 and thence through the release magnet R and the platen will be advanced one step in line space direction. If the conductor 65 is selected, the circuit will be closed through the carriage return magnet S^2 , thence by a 55 conductor 70 through a releasing magnet H^2 and thence by the conductors 71, 67 and 68 through the releasing magnet R to thereby effect the return of the carriage to commence a new line of print.

60 The two conductors 62 and 66 are arranged to control the capital and figure shift magnets H^1 and H^2 . The conductor 66 extends through the normally closed switch h^4 of the magnet H' to the normally closed switch h^5 65 of the magnet H^2 and thence to the coil of

the magnet H^2 to the ground and when this conductor is selected, the shift magnet H^2 will be operated. The conductor 62 extends through the normally closed switch h^4 of the relay H^2 through the normally closed switch h^5 of the relay or magnet H' and through the coil of this magnet, so that when this conductor is selected, the shift magnet H^1 will be operated. Each of these magnets is provided with a locking switch h^6 , the contact of which is connected by a conductor 70 to the contact of a normally closed unlocking switch h^7 that is operated by the releasing magnet H^2 and which is directly connected to the battery wire 19. The locking 75 switches h^6 are connected directly to the coils of the magnets H^1 and H^2 , so that when either of these magnets is operated, it will remain energized until the relay H^3 is operated to open the unlocking switch h^7 . The 80 switches h^5 are provided with front or normally disengaged contacts that are connected by conductors 73 to a conductor 67, so that when either of the conductors 62 or 66 is selected, it will operate one or the other of 85 the magnets H^1 or H^2 and a circuit will then be closed by one or the other of the switches h^5 to the conductors 73 and 67, through the resistance R^4 and by the conductors 68 to the releasing magnet R to open the unlocking switch r^1 . By this arrangement, the 90 operation of either of the type wheel shifter magnets H^1 or H^2 will disconnect the operating circuit of the printing apparatus from the battery so that it can print the succeeding characters. The selected one of the shift magnets, however, will remain energized to hold the type wheel in shifted position until the releasing magnet H^3 is operated, so that the succeeding signals received will print 95 capitals or figures until the proper signal is transmitted to operate the releasing magnet H^3 . The coil of this releasing magnet is connected by conductors 74 to the front or normally disengaged contacts of the switches 100 h^4 so that, after the conductor 66 has been selected to operate the magnet H^2 , the conductor 62 is connected by switch h^4 of magnet H^2 to the coil of the relay H^3 and if the conductor 62 is then selected, it will not 105 operate the magnet H^1 as usual but instead will operate the releasing magnet H^3 and the type shifter mechanism will be restored to normal condition to print "lower case" letters. Similarly, if the conductor 62 is 110 first selected to operate the magnet H^1 , the switch h^4 thereof will connect the conductor 66 to the coil of the releasing relay H^3 and the latter, if then selected, will operate the relay H^3 to restore the shifter mechanism.

115 The special shift keys F and F^1 of the transmitter, as above described, are arranged to transmit permutations both when they are depressed and when they are released. The key F^1 , when it is depressed, sends a permu- 120

130

tation consisting of five positive impulses to thereby select the conductor 66 and operate the shift magnet H^2 . The operation of this magnet will, as described, connect the conductor 62 to the coil of the releasing magnet H^3 , so that, when the key F^1 is released and transmits a negative impulse followed by four positive impulses, it will select the conductor 62 and operate the release magnet H^3 . The special shift key F transmits the same permutations but in the reverse order. That is to say, when it is depressed, it will send a permutation consisting of one positive and four negative impulses to select the conductor 62 and thereby operate the shifter magnet H^1 , and when it is released it will transmit a permutation of five positive impulses to select the conductor 66 which, at this time, is connected to the coil of the releasing magnet H^3 to thereby operate it and restore the shifter mechanism to normal condition. In this way, the shifter magnets H^1 and H^2 are controlled by two permutations which, when sent in one order will operate and release one of the magnets and when transmitted in the reverse order will operate and release the other of the shifter magnets.

To prevent the selection of these two magnets from getting out of step, the releasing magnet H^3 is connected in series with the carriage return magnet S^2 and, whenever the carriage is returned to commence a new line, the circuit through the shifter magnets will be broken and the type wheel will be restored to normal position.

The capital and figure shift magnets H^1 and H^2 are not only provided with the shiftable cores 155 and for operating the rods H^3 to thereby shift the type wheel, as described, but are also provided with armatures h^8 , (see Fig. 1) which carry and operate the several switches h^4 , h^5 and h^6 that are shown diagrammatically in Fig. 21. So also the selector operating magnets N^1 , N^2 , N^3 and N^4 are not only provided with shiftable cores N^7 but are also, as shown in Fig. 16, provided with shiftable armatures n^9 upon which the switches n^8 and the selecting switches y^1 , y^2 , y^3 , y^4 and y^5 of the fan circuit are mounted.

The relays W^5 , L^3 , and H^3 are mounted in the machine upon the upright plate 204 above the selector operating magnets, as shown in Figs. 10 and 14, and are arranged to operate pivoted armatures w^7 , l^8 , and h^9 respectively. The armature w^7 of the magnets w^5 carries the spring switch-arms w^5 , w^6 , y^6 , y^7 , y^8 and y^9 . The armature l^8 of the relay L^3 carries the switch arms l^6 and l^7 and the armature h^9 of the relay H^3 carries the unlocking switch h^7 . The transmitting and selecting relays are arranged in suitable banks outside of the machine.

It should be noted that any complete operation of the machine of the selecting and

printing apparatus consists of a number of steps, the arrangement being such that these steps must occur in succession and in proper order. Thus as the successive impulses of any permutation are received the selecting and locking devices W^1 , W^2 , W^3 and W^4 are successively connected to the line relay and are variably operated as described. The operated relays of this set are then maintained in operated condition by the locking circuits. At the end of each permutation, the locking circuit through the first four relays of this set is opened and the latter are in condition to receive and build up the next character or signal. The first four of the selecting and locking relays, as described, respectively control the selector plates, and which, together with the fifth selecting and locking magnet W^5 , control the distributing circuit to the special magnets, the type wheel rotating the other operating magnets of the printer, and when operated, are maintained in changed condition by the locking circuit these magnets or relays passing through the unlocking switch r' . At the end of each permutation the divide relay X' is operated to render the printer mechanism non-responsive to the first four selecting relays. At the same time, the circuit is closed through the shifter magnet M' which effects the movement of the stop pins into co-operative relation with the selective plates, two of the stop pins being passed through the latter, as described, in accordance with the setting of the plates. The shifter magnet then closes a circuit through the contacts m^7 and m^8 , which, if a character signal has been received, energizes one of the type wheel rotating magnets L or L' and the relay L^3 . The latter then closes the circuit through the printer magnet P and through the letter spaced magnet S . The striking movement effected by the magnet P opens the locking circuit of the printer and its parts, which together with the divide relay X' , are then restored to normal position ready to be operated in accordance with the next signal. The interpolation of the relay L^3 between the type wheel rotating magnets and the spacing and printing magnets furnishes a slight interval of time between the type wheel rotating and striking operations so that the type wheel may be fully rotated before the final printing operation is effected.

The improved apparatus and system are rapid and accurate in operation and are not liable to get out of order. It is obvious that numerous changes can be made in the details of construction and arrangement of circuits set forth without departure from the essentials of the invention as defined in the claims and that parts of the invention may be taken without its adoption in entirety.

We claim as our invention:—

1. In a printing telegraph apparatus, the combination with a type wheel, an adjusting shaft for rotating said type wheel, an arm on said shaft, a series of stops for engaging said arm to variably arrest the movement of said shaft and said type wheel, a series of oscillating selector plates concentrically mounted with respect to said shaft and controlling the setting of said stops, shifter means for variably setting said selector plates, and independent shifter means for moving said stops into position to be selected by said plates and for restoring the same to normal free from said selector plates. 70
2. In a printing telegraph apparatus, the combination with a type wheel, of an adjusting shaft for rotating said type wheel, a series of stop pins, a series of selector plates for controlling said stop pins, said pins and plates being concentrically mounted with respect to said shaft and said pins being normally held out of contact with said plates, means for setting said plates, means for shifting said stop pins into engagement with said plates to thereby project the selected pin to operative position, an arm on said shaft, and means for rotating the same to bring said arm into engagement with the selected stop pin. 85
3. In a printing telegraph apparatus, the combination with a type wheel, of adjusting mechanism for rotating said type wheel, a set of selector plates, a series of stop pins for said adjusting mechanism controlled by said selector plates, and means acting in response to the transmitted code signals for successively setting said plates, shifting said series of stop pins to project the selected pins through said plates and for rotating said type-adjusting mechanism into engagement with the selected stop pins. 95
4. In a printing telegraph apparatus, the combination with a type wheel, an adjusting shaft for rotating said type wheel, a concentric series of stop pins arranged about said shaft, a carrier whereon said pins are yieldingly mounted, a set of oscillating selector plates controlling said stop pins, means for setting said plates, means for shifting said stop-pin carrier to project the selected pin through said plates, and an arm on said shaft arranged to engage the selected pin. 105
5. In a printing telegraph in which the characters are represented by permutations of a definite number of impulses of opposite polarity, the combination with a type wheel, of a rotary adjuster therefor, a series of stop pins for variably arresting the movement of said adjuster, a set of selector plates controlling said stop pins, a corresponding series of operating magnets responsive respectively to the successive impulses of the code permutations for setting said selector plates, shifter mechanisms acting at the end of the code combination with the selected stop pin and for effecting the rotation of said type wheel adjuster into engagement therewith. 115
6. In a printing telegraph in which the characters are represented by combinations of a definite number of successive modified impulses, the combination of a type wheel, an adjuster for rotating said type wheel, a series of stops for arresting the rotary movement of said adjuster and said type wheel, a set of selector plates controlling said stops, striker mechanism for effecting the imprint of the selected type, electromagnetic means variably responsive to the successive impulses of the code combinations for setting said selector plates, and electromagnetic devices acting at the end of the completed code combination for positioning the selected stop, effecting the rotation of said type wheel and actuating said striker mechanism. 120
7. In a printing telegraph in which the characters are represented by permutations of a definite number of impulses of opposite polarity, the combination of a type wheel, a rotary adjuster therefor, a series of stop pins for variably arresting the movement of said adjuster, a set of selector plates controlling said stop pins, said plates and pins being concentrically arranged with respect to said rotary adjuster, a series of operating magnets corresponding with said plates and variably responsive to the successive impulses of the code permutations for setting said plates, a shifter for effecting the movement of said stops into engagement with said plates and the shift of the selected stop into operative position, means for rotating said adjuster and type wheel, striker mechanism for effecting the imprint of the selected type, electromagnets for controlling said stop shifter, said type wheel rotating means, and said striker mechanism, and means acting at the end of the completed permutation for energizing said stop shifter magnet, the latter being arranged to control the circuit of said type wheel rotating magnet, and said type wheel rotating magnet being arranged to control the circuit of said striker magnet, whereby the operations of said magnets are effected in succession. 125
8. In a printing telegraph in which the characters are represented by combinations of a definite number of successive modified impulses, the combination of a type wheel, a series of stops for variably arresting the rotary movement of said type wheel, a set of selector plates controlling the setting of said stops, a corresponding series of operating magnets responsive respectively to successive impulses of the code permutations for setting said selector plates, shifter mechanisms acting at the end of the code combination with the selected stop pin and for effecting the rotation of said type wheel adjuster into engagement therewith. 130

- nation for successively projecting the selected stop to operative position, rotating the type wheel and effecting the printing of the selected type, a number of electromagnets controlling the successive operations of said shifter mechanisms, a locking circuit for said electromagnets, and means acting after the printing of a letter for opening said locking circuit.
- 10 9. In a printing telegraph apparatus, the combination with a type wheel and its adjusting shaft, of a concentric series of stop pins arranged about said shaft, a series of oscillating selector plates arranged to select 15 said stop pins in pairs and means for rotating said adjusting shaft in opposite directions from normal into engagement with one or the other of the pair of selected stops.
10. In a printing telegraph apparatus, the combination with a type wheel and an adjusting shaft connected to rotate said type wheel, of a concentric series of stop pins arranged about said shaft, an arm on said shaft coöperating with said stop pin, a series of oscillating selector plates for selecting 25 said stop pins in pairs and means acting in response to the code signals for successively setting said selector plates, shifting said pins to project the selected pair 30 into the path of movement of said arm and for rotating said shaft and type wheel in one or the other direction to bring said arm into engagement with one of the selected stop pins.
- 35 11. In a printing telegraph in which the characters are represented by permutations of five impulses of opposite polarity, the combination with a type wheel yieldingly held in central position, of a series of stops for variably arresting the movement of said type wheel, a set of four selectors acting in 40 response to the first four impulses of any permutation to select said stops in pairs and means acting in response to the last impulse 45 of any permutation for rotating said type wheel in one or the other direction until arrested by one of the selected stops.
12. In a printing telegraph in which the characters are represented by permutations of a definite number of impulses of opposite polarity, the combination with a type wheel and rotary adjusting mechanism therefor, said type wheel and its adjusting mechanism being yieldingly held in central position, a series 55 of stops for variably arresting said adjusting mechanism, a set of selectors arranged to select said stops in pairs, means acting in response to the last impulse of any permutation for projecting the selected pair 60 of stops and rotating said type adjusting mechanism in one or the other section from normal into engagement with one of the selected stops and means acting in response to the other impulses of the permutations for 65 variably setting said selectors.
13. In a printing telegraph apparatus, the combination with a type wheel, of an adjusting shaft for rotating said type wheel, spring mechanism for yieldingly holding said shaft and said type wheel in central 70 position, a sliding carrier extending about said shaft, a circular series of stop pins yieldingly mounted on said carrier, a set of oscillating selector plates mounted on said shaft and arranged to select said stop pins 75 in pairs, an arm on said shaft arranged to engage the selected stop pins and electromagnets acting in response to the impulses of the code signals for successively setting said selector plates, shifting said carrier to 80 project the pair of selected pins into the path of movement of said arm and for rotating said shaft in one or the other direction from normal into engagement with one of the selected pair of stop pins. 85
14. In a printing telegraph in which the signals are represented by permutations of a definite number of modified impulses, the combination of a type wheel having a normal central position, a set of stops for variably arresting the movement of said type wheel, a set of selector plates arranged to select said stops in pairs, means for shifting said type wheel in opposite directions from central position into engagement with one 90 of the selected pairs of stops, a set of electromagnets responsive to certain of the impulses of each permutation for setting said selector plates, and an electromagnet means responsive to the remaining impulse or impulses of the permutation for controlling the direction of rotation of said type wheel. 100
15. In a printing telegraph apparatus, the combination with a type wheel, and an adjuster for rotating said type wheel in opposite direction from normal, of two heavy, oppositely acting restoring springs connected to said type wheel adjuster, a pair of oppositely acting, spring-held, centering devices each having a one-way engagement 105 with said type wheel adjuster, and a fixed stop with which said centering devices normally engage. 110
16. In a printing telegraph apparatus, the combination with a type wheel, of an adjusting shaft geared to said type wheel, a drive shaft, a gear segment on said drive shaft, a pinion on said adjuster shaft engaging said gear segment, a cross arm on said drive shaft, a pair of magnets acting on opposite ends of 115 said cross arm for shifting said shafts and type wheel in opposite directions from normal, a pair of heavy, oppositely acting restoring springs connected to said drive shaft, a pair of oppositely arranged centering 120 arms loosely mounted on said adjusting shaft, an arm on said adjusting shaft interposed between said centering arms, a fixed stop interposed between said centering arms 125 and a spring for holding said centering arms 130

into engagement with said fixed stop and the arm on said adjusting shaft.

17. In a printing telegraph apparatus, the combination with a rotary, type-adjusting mechanism movable in opposite directions from normal-central position, and spring devices for restoring the same to normal, of a stop arranged to be projected into position to arrest the return movement of said adjusting mechanism and means shifting said stop to release said adjusting mechanism for the succeeding operation.

18. In a printing telegraph apparatus, the combination with a type wheel and an adjusting shaft for rotating said type wheel in opposite directions from normal, of a set of stop pins for variably arresting the operative movement of said shaft, a back-stop for arresting the return movement of said shaft, and selector mechanism for selecting and shifting said stop pins to operative position and for shifting said back-stop to inoperative position.

19. In a printing telegraph in which the signals are represented by combinations of modified impulses, the combination of a type wheel having a number of sets of type arranged in rows, a shifter mechanism responsive to special code signals for axially shifting said type wheel to bring any one of the rows or sets of type thereon opposite the printing point and for maintaining the type wheel in such position during the reception of succeeding code signals, an adjusting device for rotating said type wheel, a series of stops for variably arresting the rotary movement of said adjusting device and said type wheel, a set of selector plates for controlling said stops, means responsive to the successive impulses of the code signals for setting said plate, and means acting at the end of the code signals for projecting the selective stop, rotating the type wheel and effecting the imprint of the selected type.

45 20. In a printing telegraph apparatus, the combination with a type wheel, of a shaft for rotating said type wheel, a series of stop pins and a series of selector plates concentrically mounted with respect to said shaft, a set of electromagnets for shifting said plates, means for shifting said stop pins into and out of engagement with said plates, an electromagnet for actuating said shifter means, an arm on said shaft, and means for rotating said shaft to bring said arm into engagement with the selected pins.

21. In a printing telegraph in which the characters are represented by permutations of a definite number of impulses of opposite polarity, the combination with a type wheel, of a rotary adjuster therefor, a series of stop pins and set of selector plates for controlling said stop pins, said pins and plates being concentrically mounted with respect to said rotary adjuster, a series of operating mag-

nets responsive to the successive impulses of the code permutations for setting said selector plates, electromagnetic means acting at the end of each permutation for shifting said stop pins into engagement with said plates, and means for rotating said type wheel adjuster into engagement with the selected stop pin.

22. In a printing telegraph apparatus, the combination with the printing mechanism, of shift mechanism therefor for selecting any one of a number of sets of type, two magnets arranged to variably operate said shift mechanism, a locking circuit for said shift magnets, a releasing magnet for opening said locking circuit, said shift and releasing magnets acting in response to two special code signals, one of said shift magnets and said releasing magnet being responsive to the transmission of the two special code signals in one order and the other of said shift magnets and said releasing magnet being responsive to the transmission of the same code signals in the reverse order.

23. In printing telegraphs, the combination with transmitting mechanism, of two special shift keys therefor, each arranged to transmit a special code signal when depressed and another special code signal when returned to normal position, said keys transmitting the same code combinations but in reverse order, a printing receiver having a number of sets of type, shift mechanism for selecting any one of the sets of type, and means responsive to the transmission of the two special signals in different orders for variably operating said shift mechanism to select different sets of type and to restore the shift mechanism to normal position.

24. In a printing telegraph apparatus in which the signals are represented by permutations of a definite number of impulses of opposite polarity and of substantially uniform length, the combination with a type wheel, a shaft whereon said type wheel is mounted, an oscillating frame in which said shaft is journaled, shift mechanism for moving said type wheel longitudinally on its shaft to bring any one of the number of rows of type thereon to printing position, adjusting mechanism for variably rotating said shaft and type wheel, electric selective means controlling said type wheel shift and adjuster mechanisms, striking mechanism for shifting said type wheel laterally to print the selected type and electric means acting at the end of the completed code signals for operating said striker mechanism and for shifting the type wheel in letter space direction.

25. In a printing telegraph apparatus in which the characters are represented by permutations of a definite number of impulses of opposite polarity and of substantially uniform length, the combination with a ro-

- 6 tary type wheel having a number of rows of type thereon, of a shaft whereon said type wheel is mounted, a sliding carriage shiftable in letter space direction, an oscillating frame or arm on said carriage wherein said type wheel shaft is journaled, shift mechanism movable with said carriage for moving said type wheel longitudinally on its shaft to bring any one of the rows of type 10 thereon to printing position, adjuster mechanism on said carriage for rotating said type wheel, striker mechanism on said carriage for shifting said oscillating frame or arm and said type wheel to print the selected 15 type, electric selective means controlling said wheel adjuster and shift mechanisms and electric means acting at the end of the completed code signals for operating said striker mechanism.
- 20 26. In a printing telegraph apparatus, the combination with a rotary type wheel having a number of rows of type thereon, of a shaft whereon said type wheel is mounted, a sliding carriage shiftable in letter space 25 direction, an oscillating frame or arm on said carriage wherein said type wheel shaft is journaled, shift mechanism movable with said carriage for moving said type wheel longitudinally on its shaft to bring any one 30 of the rows of type thereon to printing position, adjuster mechanism on said carriage for rotating said type wheel, striker mechanism on said carriage for shifting said oscillating frame or arm on said type wheel to 35 print the selected type, a set of three operating shafts, whereon said carriage is slidable, connected respectively to said type wheel shift and adjuster mechanisms and to said striker mechanism, and electric selective 40 means acting in response to the transmitted code signals for controlling the operation of said shafts.
27. In a printing telegraph apparatus, the combination with a paper support, of a carriage shiftable in letter space direction, a set 45 of shafts whereon said carriage is slidable, an oscillating arm pivoted on said carriage, a type wheel rotatably mounted on said arm and geared to one of said shafts, a striker 50 mechanism mounted on said carriage, connected to said oscillating arm and operated by one of said shafts, electric selective means controlling the operation of said shafts, and means acting at the end of the completed 55 code impulses for shifting said carriage step by step in letter space direction.
28. In a printing telegraph apparatus, the combination with a paper support, of a carriage shiftable in letter space direction, a set 60 of shafts whereon said carriage is slidable, an oscillating arm pivoted on said carriage, a rotatable and axially movable type wheel mounted on said arm and geared to one of said shafts, striker and type wheel shift 65 mechanisms carried by said carriage and

connected to other of said shafts, electric selective means controlling the operation of said shafts, and means acting at the end of the completed code signals for shifting said carriage step by step in letter space direction. 70

29. In a printing telegraph apparatus, the combination with a carriage shiftable in letter space direction, of a type wheel mounted on said carriage, electric selective means controlling the operation of said type wheel, a spring drum connected to said carriage, a winding drum connected to said carriage for shifting the same in letter space direction against the tension of said spring drum, a ratchet wheel fixed to said winding drum, feeding and retaining pawls coöoperating with said ratchet wheel, a magnet for operating said feed pawl upon the restoring shift of its armature, means for disengaging said feeding and retaining pawls from said ratchet wheel to permit the return movement of the carriage, a stop device for preventing the overthrow of said winding drum upon the return movement of the carriage, and an electromagnet for operating said pawl disengaging means. 85

30. In a printing telegraph apparatus, the combination with a type wheel shiftable in letter space direction, and electric selective 95 means controlling the operation of said type wheel, of a rotary paper platen, a pair of fixed supports wherein said platen is journaled, a line space ratchet fixed to said platen, a shifting arm carrying feeding and stop pawls coöoperating with said ratchet, said arm normally holding said pawls out of engagement with said ratchet, and an electromagnet for acting in response to the transmission of a special code signal for 100 shifting said arm.

31. In a printing telegraph, the combination with a type wheel, of an oscillating arm whereon said type wheel is rotatably mounted, electric selective means variably 110 rotating said type wheel, striker mechanism for oscillating said arm and said type wheel to print the selected type, a centering device pivotally mounted on said oscillating arm at a distance from the center of oscillation 115 thereof whereby said centering device is moved by said arm, a toothed wheel connected with said type wheel, and a part for shifting said centering device into and out of engagement with said toothed wheel as 120 said arm and type wheel are oscillated by said striker mechanism.

32. In a printing telegraph apparatus, the combination with a type wheel and platen, of an oscillating arm whereon said type 125 wheel is rotatably mounted, a carriage that is shiftable step by step in letter space direction whereon said oscillating arm is pivoted, electric selective means for variably rotating said type wheel, striker mechanism acting in 130

- response to the completed code signals for shifting said arm and type wheel laterally to bring the selected type to the printing point on the platen, a support on said carriage extending beneath the platen, an arm pivoted on said support and an inking roller on said arm intermediate the type wheel and the platen, said type wheel being arranged to shift said inking roller out of its path of movement when said striker mechanism is operated.
33. In an electric telegraph apparatus, the combination with a rectangular base frame, a series of key levers pivotally mounted in said frame and having finger keys at their forward ends, a set of selecting switches variably controlled by said keys, a top frame mounted on said base plate, a paper platen journaled on the upper portion of said top frame, a sliding carriage movable in letter space direction arranged within the upper portion of said top frame, a type wheel supported by said carriage in front of said platen, a series of shafts journaled in said top frame whereon said carriage is slidable, type wheel shifting, rotating and striking mechanisms connected to said carriage and operated by said shafts, a letter space feed mechanism connected to said carriage, a line space feed mechanism for advancing said platen and a series of electro-magnets arranged within said top frame for operating said line and letter space feed mechanisms and said type wheel controlling shafts.
34. In a printing telegraph apparatus, the combination with a type wheel and rotating adjuster mechanism therefor, of a set of

stops for limiting the movement of said adjuster mechanism, a set of selectors controlling said stops, a set of magnets for operating said selectors, means acting in response to the impulses of the code signals for variably controlling the circuits of said magnets, carriage return, line space and letter space feed mechanisms, special magnets for operating said mechanisms and a set of switches controlled by said selector operating magnets for controlling the circuits of said special magnets.

35. In printing telegraphs, in which the signals are represented by permutations of a definite number of successive modified impulses, the combination of an adjusting shaft, a type wheel connected to rotate with said shaft but shiftable independently thereof in letter space direction, a series of shiftable stops concentric with said shaft for arresting the rotation thereof, a set of stop-controlling selector plates, a set of electro-magnetic shifters responsive respectively to separate impulses of the permutations for shifting said selector plates, and separate electro-magnetic shifter mechanisms acting at the end of the permutations for successively controlling the setting of the selected stop in operative position, the rotation of said type wheel, the printing of the selected type and the movement of the type wheel in letter space direction.
